AUTOMATIC SWITCHING SYSTEM AND APPARATUS

Edward E. Kleinschmidt, Highland Park, and David S. Hulfish, Chicago, Ill., assignors to Teletype Corporation, Chicago, Ill., a corporation of Delaware

Application December 13, 1929, Serial No. 413,838
Renewed July 25, 1932

79 Claims. (Cl. 179—4)

Our invention relates to automatic switching systems and apparatus therefor. More particularly the invention relates to automatic switching systems and apparatus for combined telegraph and telephone or other combined signalling operations.

5 Due to the difference in characteristics between telegraph and telephone signals, the former being characterized by direct periodic current marking and spacing signal impulses and the latter by a continuous oscillating current of speech frequency, difficulty has been experienced in permitting both telephone and telegraph operation over the usual automatic telephone switching mechanism. As is well known, automatic switching systems are operated by dialed direct current signal impulses to which switching equipment responds for selecting the called party line. Release of the equipment is ordinarily accomplished by the disconnection of the direct current for a predetermined interval when the subscriber hangs up. It will be evident that in such a system, the automatic equipment would be normally unable to distinguish between the dialing 10 signalling impulses and the telegraph signalling impulses and the direct current telegraph signals would furthermore experience difficulties in passing over telephone lines designed primarily for the transmission of speech frequencies.

15 In general, the invention contemplates a separate signalling number for each telephone and telegraph set even where a single subscriber is provided with both types of sets. The switching equipment is arranged to connect all telegraph numbers through translating and repeating equipment which after connection has been completed through to the called subscriber, translates at the calling end of the system direct current signals originating at the calling subscriber's apparatus into alternating current of substantially speech frequency and retranslates the alternating currents at the called subscriber's end of the system into direct current signal impulses for operating the receiving apparatus. Provision is also made for permitting telegraph signalling in both directions following connection and for restoration of the switching equipment at the end of communication.

20 Although each subscriber is provided with a single signalling circuit to the switching equipment, provision is made for distinguishing between a telegraph and telephone call by a difference in frequency of the ringing current in each case.

25 At each of the stations, sets are arranged to

permit calling of any other set at any other station. When the station desired is equipped with both a telephone set and a telegraph set, the desired set, telephone or telegraph, is indicated and is selectively connected to the line at the responding station by reason of the signals of the directory number which has been dialed by the calling station. Many or all of the automatic switches of the telephone central offices may be used for either telephone or telegraph connections. The trunk lines connecting several offices of an exchange may be used for either telephone or telegraph communications alternatively.

30 Similarly the metering for totalizing telephone and telegraph calls is selectively accomplished by distinguishing between telephone and telegraph signalling.

Accordingly an object of our invention is to provide novel means for adapting standard and well known types of telephone exchange apparatus to the co-operative service of telephone and telegraph switching.

35 A further object of our invention is to provide novel exchange systems in which two telephone sets may communicate as in an exchange which is exclusively telephonic and without being in any way inconvenienced by the presence of telegraph apparatus and in which also two telegraph sets may communicate by telegraphy, the connections being set up in the manner of a telephone connection with the use of telephone types of calling dials.

40 A still further object of our invention is to provide standard switches and circuits to enable the owner of an automatic telephone exchange provided with no telegraph service to add a minimum equipment for producing an exchange suitable for both classes of service; namely, telephonic and telegraphic.

45 Still another object of our invention is to provide an automatic exchange system in which telegraphic service is added without diminishing the telephonic value of the service.

Further objects of an invention are to provide 50 metering means for totalizing the telegraph calls of a line separately from the telephonic calls of the same line and to provide signals on a set of apparatus for warning against an attempt to use the set at a time when an alternative set upon the same line may be in use. Alternate forms of apparatus are shown and other objects will be clear from the drawings and description, and from the scope of the appended claims.

In the drawings:

Figure 1 is a diagrammatic view of the tele-

55

graph and telephone signalling circuit from calling to called subscriber before connections therebetween have been made.

130 Figure 29 is a circuit diagram of another modified form of repeater system with the details of Figure 22 substituted in the system of Figure 28.

135 In Figure 1, two subscriber stations, 1 and 2, remotely disposed from each other are shown, each station being provided with a telephone set and a telegraph set, as shown in detail in Figure 7. Extending from each of these sets are

their individual signalling lines 3, 4 and 5, 6, respectively, over which either telephonic or telegraphic communications may be carried on depending, as will appear more fully hereinafter, upon the number dialed. Each of such stations, as 1 or 2, which is provided with telegraph and telephone equipment, is also provided with two directory numbers for its single signalling line, one being a telephone number and the other a telegraph number.

140 The signalling lines 3 and 4 extend to the usual form of rotary line switch 7, shown diagrammatically in Figure 1 and in detail in Figure 3, which is of well known construction and operates in response to the lifting of the telephone hook at the station 1 to find the first idle selector such as selector 8, the wipers of which are connected over conductor 9 to the third contact on the rotary switch 7. It will be understood that similarly each of the other contacts of the rotary switch 7 has associated therewith a similar selector 8 connected to a conductor such as 9. Selector 8, which is also of any well known construction commonly used in the telephone art and is shown in detail in Figure 3, operates in response to the first dialing signal at the station 1 to move the wipers of the selector to predetermined contacts.

145 The selector 8 is merely shown diagrammatically in Figure 1. It comprises a plurality of contacts arranged in horizontal rows, there being a number of these rows disposed one above the other. In operation, after the wiper 18 has moved vertically to select a predetermined row of contacts it automatically rotates in a horizontal plane until it reaches a contact connected to an idle selector.

150 The conductor 10 extending from conductor 9 is shown in dotted lines to illustrate diagrammatically that it is normally open and is closed when the selector completes its operation. If the first dialed signal is a telephone signal, the circuit over conductor 9 is extended over conductors 10 and 11 to a selector repeater 12. If on the other hand, the first dialed signal is a telegraph signal, the circuit over conductor 9 is extended over the conductors 10 and 13 to a repeater 14, which, as will appear hereinafter more fully from the detailed description, is arranged to transmit the telegraph codes over the signalling lines after connections have been made with the remote or called subscriber's station.

155 Upon operation of the repeater 14, a rotary line switch 15 of construction similar to the rotary line switch 7, briefly described above, is operated until it finds an idle selector 16. Upon the dialing of the second telegraph selecting signal the selector 16 operates to select a line such as 17 connected in multiple with the conductor 11 and extending to the selector repeater 12. The repeater 12 is thereupon operated in accordance with the next or third telegraph selecting signal dialed.

160 It will be noted that the dialing of the second and third telegraph selecting signals produces the same result as the dialing of the first and second telephone selecting signals in that in either case connections are established between the station 1 and a selector repeater 12. The dialing of the first signal in the case of telegraph merely functions to insert the repeater 14 in the signalling system.

165 In the present case, the connection to be made will be based on the assumption that the station 2 has been assigned a telephone number of South 75

8644 and a telegraph number of telegraph South 8855. These two numbers are dialed S. O.—8644 and T. S. O.—8855, respectively. It will be assumed that station 1 is the calling station and station 2 is the called station.

For telephonic communication accordingly the subscriber at station 1 lifts the receiver and dials S. O. 8644. Upon lifting the receiver, the rotary line switch 7 responds thereto in the well known manner and rotates until it finds the first idle selector which in the present case is the selector 8, the operation of which will be described more fully hereinafter. The effect of dialing the letter S is to lift the brushes of the selector 8 seven steps and to connect the conductor 3 and 4 of the station 1 through the wipers on the rotary line switch 7 on which it has stopped and conductor 9 through the wipers 18 to the conductor 11 extending to the repeater 12. Dialing the letter O lifts the brushes of the selector repeater 12, in a manner to be described, through six steps and extends the circuit traced above over the conductors 21 and 22 to a third selector 28 at the remote exchange, selector 28 being of construction similar to selector 8.

Before tracing the further operation of dialing the telephone number, the effect of dialing a telegraph number up to this point will be briefly described. For telegraphic communication, the party at station 1 operates a starting key of a telegraph set corresponding to the hook switch of the telephone set, as will appear in detail hereinafter, and dials T. S. O.—8855.

Upon operation of the starting key, the line switch 7 responds, as described above, to select the first idle selector switch 8 over the conductor 9. Dialing the letter T lifts the brush 18 eight steps and connects the station 1 to the repeater 14 over the conductor 13. The relay 23 comprising part of the repeater 14 is operated over this circuit and at its armature 24 closes a circuit through the retardation coil 25 and through the rotary line switch 15 which is now operated in the same manner as rotary line switch 7 to find the first idle selector such as selector 16.

The switching dial impulses produced by dialing the letter S from the station 1 will now be repeated by the relay 23 of the repeater 14 and will move the wipers 26 of the selector 16 seven steps extending the circuit over conductor 17 to the selector repeater 12 as in the case of the telephone selection. When now the letter O is dialed, the brush 27 is raised six steps extending the circuit over conductor 21 as in the case of the telephone communication.

At this point it will be noted that in the case of the telephone selection the operation of dialing the letter S operates the selector 8 to connect through directly to the selector repeater 12 whereas in the case of the telegraph selection the operation of dialing the letter T extends a circuit from the station 1 over conductor 13 through the telegraph repeater 14 which in turn causes operation of the rotary line switch 15, the rotary line switch thereupon operating to select the first idle selector 12.

The conductors 21 and 22 are connected to a brush 32 moving over contacts of a selector 28 and the selector 28 will be operated as in the case of selector 8 to extend a circuit over conductors 21 and 22 and over conductor 34 to wiper 35 of a selector 37.

It will be noted upon referring to the telephone and telegraph numbers again that the first numeral of both the telephone and telegraph code

are alike, both being 8. In response to eight impulses, the brush 32 of the selector 28 is stepped over eight contacts to extend the circuit as stated above over conductor 34 to the brush 35. If now, the telephone number is being dialed and six impulses are received, brush 35 will move to the sixth contact extending a circuit over conductors 38 to the connector switch 39. The connector 39 now will operate in response to the dialing of the last two numbers 4—4 to extend telephone circuits 10 from conductor 38 over conductors 5 and 6 completing the circuit to the called station 2.

If on the other hand, the telegraph number is being dialed and eight impulses are received, the brush 35 will be stepped to the eighth contact 15 extending the circuit over conductor 34 and the conductor 41 to the telegraph repeater 42. The telegraph repeater 42 comprises a dialing impulse repeating relay 43, telegraph receiving relay 45, telegraph repeating relay 48 and a source of 20 alternating current 46. Armature 47 of relay 48 is also part of repeater 42 and operates to repeat impulses in the opposite direction, as will appear more fully hereinafter. Relay 45 is operated in response to received telegraph signalling impulses 25 to operate its armature 51 for operating the called party's telegraph apparatus after connection has been completed in accordance with the next two dialed numbers 5—5. The armature 51 is connected to the wipers 52 of a connector 53. The connector 53 operates in response to the last two dialed numbers 5—5, completing the circuit over conductors 54 to the lines 5 and 6 and to the called station. In this case also the distinction 30 between the telephone and telegraph circuits 35 completed resides in the fact that in the telegraph circuit the telegraph repeater 42 is included in the circuit as is the telegraph repeater 14 at the calling station end of the system.

When the connection to the called station 2 is 40 made through the telegraph repeater 42 in the manner described above, ringing current is impressed over the conductors 5 and 6 to the called station 2 which will operate in a manner to be described to remove the telephone set from the 45 line and connect the telegraph set to the line.

A polar relay at the called station 2 will be controlled by current of reversed polarity on the line, the current from the final connector 53 being reverse in direction as compared with current 50 from the final connector 39 and will retain the telegraph set upon the line until the release of the connection, when current through this relay will release the telegraph set and will replace the telephone set and the signalling devices upon the 55 line.

The calling station 1 is shown in detail in Figure 7, and, as will appear hereinafter, comprises a telephone set and a telegraph set.

Because the numerical selected impulses originated by the calling dial of the telegraph set must pass through the repeater 14, the calling dial of the telegraph set may be adjusted to operate at a lower speed than the calling dial of the telephone set if desired. Should the feature 60 of two adjustments be used, the telephone set calling dial is not restricted in any way since the numerical currents from the telephone set do not encounter any retardation such as 25 in the repeater 14.

Figure 7 shows the details of the calling station comprising a telephone and a telegraph set, a telephone receiver 61, transmitter 62 and hook 63 therefor, all of well known construction and connected in the well known manner to the usual 75

form of telephone dial 64. One terminal of the telephone dial 64 is connected over the conductor 65 to the telephone equipment described above, the switch operating with two contacts, one of which is connected to conductor 66 and the other to the conductor 67. Conductor 66 extends to the upper contact of a switch arm 68 which in turn is connected to the conductor 4 extending to the rotary line switch as shown in Figure 1.

10 The other conductor 67 extends to the upper contact of the switch arm 69 which in turn extends over the conductor 3 to the other side of the rotary line switch as shown in Figure 1. Switch arms 68, 69, 71, 72 and 73 are operated 15 by the vertical arm of change-over switch 74 controlled by the telegraph start lever 75 of any well known construction.

The switch arm 68 when in engagement with its lower contact, as will appear more fully hereinafter, extends a circuit over the conductor 81, contacts 83 and 84, through the polar relay 85, printer magnet 86, transmitter 87 and the contacts 88 controlled by the omnigraph dial 89, contact of impulse dial 82 and lower contact of switch 25 arm 68.

Having described the general arrangement of the invention, details of the various apparatus employed will now be described. It will be assumed that the subscriber shown in Figure 7 desires to call the subscriber in Figure 8 for telegraph communication.

Dialing for telegraph communication

In order to initiate telegraph communication, 35 the operator at the calling station 1, Figure 7, operates the starting key 75 which in turn moves the change-over switch 74 moving the switch arms 68, 69, 71, 72 and 73 to their lower position and a holding circuit is closed from ground, 40 through battery, winding of the magnet 91, switch 72 and its contact, switch 92 and its contact, conductor 93 to the lower contact and switch spring 94 of the telephone hookswitch, to ground. Magnet 91, upon energization, holds the change-over 45 switch 74 in the operated position. An obvious energizing circuit is also completed over the switch 73 for the normally non-operating motor 94' of the telegraph set which is now started into 50 operation. A further result of the operation of change-over switch 74 is to complete a circuit for the signalling lamp 95 over the switch arm 71 indicating that the telegraph apparatus is in operation so that the telephone user will not attempt to use the telephone set at this time. A 55 similar circuit may be completed over the hook switch spring 94 and conductor 96 to the signalling lamp 97 to indicate to the telegraph operator when the telephone user has seized the line associated therewith for communication. A further 60 result of the operation of change-over switch 74 is to connect the conductors 3 and 4 over the switch arms 69 and 68, respectively, to the telegraph apparatus over the conductor 81 and the telegraph dialing equipment.

65 As a result of this latter operation an energizing circuit is completed for the slow-to-release line relay 101 shown in Figure 3, which relay is part of the rotary line switch 7, the circuit extending from ground, through battery, winding 70 of line relay 101, the back contact and armature 108 of a cut-off relay 109, over the conductor 4, through the switch arm 68 in engagement with its lower contact, through the contact of the dial 82, contact 88, transmitter 87, through the printer 75 magnet 86, polar relay 85, contacts 84 and 83 in

parallel, conductor 81, switch arm 69 in engagement with its lower contact, conductor 3 and armature 112 and its back contact to ground.

The line relay 101 of the rotary line switch 7 is thus energized in response to the changeover 5 operation of the telegraph starting key 75 at the calling station 1.

The rotary line switch 7 comprises, in addition to the line relay 101, a cut-off relay 109 and a motor magnet 113 which controls a set of wipers 10 114 causing them to pass step by step over a bank of contacts 115. The construction of the wipers 114 and bank is such that the wipers will at all times be in engagement with a set of bank contacts 115. To each of the bank contacts 115 are 15 connected the customary positive and negative trunk 116, 117 and release trunk 118, leading to the selectors such as selector 8.

If the rotary line switch wipers are resting on a busy trunk when the line relay 101 becomes energized, the cut-off relay 109 will be shunted out and a circuit will be completed from trunk 116 which is at this time grounded, as will appear hereinafter, and over contact 115, brush 114, armature 131 of the cut-off relay 109 in engagement with its back contact, armature 132 of the line relay 101 in engagement with its front contact, contact and armature 122 of the motor magnet 113 and through the winding of magnet 113, 20 to battery and ground.

The motor magnet 113 will now operate and advance the wipers 114 step by step as it is energized and deenergized by the operation of its armature 122. In this manner, the cut-off relay 109 remains shunted out so long as the wiper 114 35 engages a private busy bank contact 115. When, however, an idle trunk is reached, the shunt circuit mentioned above is absent, and the cut-off relay 109 will be energized over a circuit from ground, through the armature 121 of the line relay 101 and its front contact, through the winding of the cut-off relay 109, the back contact and armature 122, the winding of the motor magnet 113, and battery to ground. The motor magnet 113 is so constructed that it will not energize when 40 in series with the cut-off relay 109. Cut-off relay 109 will, however, energize over the above traced circuit and operate to extend the connections from conductors 4 and 3 over armatures 108 and 112 respectively, in engagement now with their 45 front contacts, over conductors 123 and 124, respectively, wipers 114, contacts 115 and trunks 50 117 and 118 to the selector.

When cut-off relay 109 energizes, it opens the circuit of line relay 101 at armature 108 and moves armature 131 into engagement with its front contact. Relay 101, being a slow acting relay, will not immediately deenergize, but will maintain ground on the release trunk until sufficient time has elapsed for the release relay of the 60 selector 8 to provide a new holding ground on the release trunk, for the cut-off relay 109 from battery, through motor magnet 113, armature 122 and its back contact, cut-off relay 109, front contact and armature 134, wiper 114 and conductor 116 which is grounded as will be described. Immediately after this holding circuit for cut-off relay 109 is established, the line relay 101 will be deenergized.

In this manner the rotary line switch 7 operates in response to the operation of the starting key 75 at the calling station 1 to rotate its wipers until they find a group of trunks 116 to 118 extending to an idle selector, such as selector 8. The conductors 117 and 118 now extend a circuit 75

from the calling station 1 over armatures 133 and 134, respectively, and through the two windings of the line feed relay 135.

The line feed relay 135 is energized and at its armature 136 completes an obvious energizing circuit for the release relay 137 which is of the quick-to-operate type. Release relay 137, upon energization, moves its armature 138 into engagement with its front contact and extends ground 10 to the trunk 116 connected to the bank contact 115 for locking the relay 109 as described above and also to provide ground for any other wiper 114 of any other rotary line switch moving over this contact for shunting its associated cut-off 15 relay and continuing the operation of its associated motor magnet as described in connection with the rotary line switch 1. When the upper wiper 114 engaged the upper private contact 115 no ground appeared on this trunk inasmuch as 20 the selector 8 in the above was assumed to be in an idle condition.

The operations thus far described are those which take place automatically in response to the original operation of the starting key 75, the first 25 idle selector 8 having been selected. It is assumed, as state above, that the telegraph code T. S. O. 8855 is being dialed and that at this time the letter T is dialed. As the letter T is dialed, the line feed relay 135 is periodically deenergized 30 and reenergized. At the first deenergization of the line feed relay 135 in the dialing operation, a circuit is completed from ground, through armature 136 in engagement with its back contact, back contact and armature 141, armature 142 in engagement with its front contact, through the winding of the slow-to-release series relay 143 35 and through the winding of the vertical magnet 144, to ground.

The slow relay 143 is energized and will remain 40 energized until the last of the group of impulses representing the letter T is dialed, inasmuch as the deenergizing intervals between the impulses are too short to deenergize relay 143. The vertical magnet 144 is energized to step the wipers 18 from one level of contacts 150 to the succeeding level of contacts 150. At the first step of the wipers by the vertical magnet 144 the off-normal 45 switch 153 closes its contacts.

As is well known in the art, the release relay 50 137, the circuit of which is periodically opened as the armature 136 moves to its back contact, is not deenergized during these intervals, its construction being such that insufficient time is provided during the ordinary impulsive interval to permit relay 137 to become deenergized. In the present case, it is assumed that eight such impulses are transmitted and the vertical magnet 144 is accordingly energized eight times moving its brushes 18 step by step until they reach the 55 eighth row of selector contacts on the selector 8 as shown in Figure 1.

Energization of the slow relay 143, operates its 60 armature 145 to engage its front contact, and the ground at armature 138 is extended over armature 145 and its front contact and over the back contact and armature 146 of the rotary magnet 147 and then over conductor 148, to relay 161, but this has no effect at this time due to the ground obtained at the opposite terminal 65 of relay 161. A circuit is also completed from the ground, over armature 145 and its front contact, over conductor 151 to the contact 152 of the off-normal switch 153, and through the winding of the private relay 154 to battery and ground. 70 Relay 154 energizes and closes a locking circuit 75

for itself from ground and battery, through the winding of the relay 154, contact 152 of off-normal switch 153, conductor 151, back contact and armature 146, armature of relay 154 to ground.

At the end of the dialing impulsive, relay 135 5 remains energized sufficiently long to in turn de-energize relay 143 which moves its armature 145 into engagement with its back contact establishing a circuit for rotary magnet 147 from ground, through battery, through the winding of the rotary magnet 147, front contact and armature 156, back contact and armature 145, armature 138 and its front contact to ground. Rotary magnet 147, upon energization, prepares the wipers 18 for stepping over the contacts 150 and 15 moves its armature 146 out of engagement with its back contact thereby breaking the locking circuit of private relay 154 and de-energizing this relay. De-energization of private relay 154 opens the circuit of rotary magnet 147 at armature 156. 20 De-energization of rotary magnet 147 rotates the wipers 18 into engagement with a set of contacts 150.

If the repeater to which these contacts are connected is busy, conductor 150' will have 25 ground on it, as will appear hereinafter, and a circuit will be completed from grounded conductor 150', contact 150, wiper 18, conductor 139, armature 140 in engagement with its back contact, conductor 148, armature 146 in engagement 30 with its back contact, conductor 151, off-normal contact 152, winding of private relay 154 to battery and ground. Private relay 154 will be energized, moving armature 156 into engagement with its front contact, again energizing rotary 35 magnet 147. This magnet will then rotate the wipers 18 into engagement with the succeeding set of contacts 150 on the same level. If the repeater to which these contacts are connected is busy, the above-described operation will be repeated. 40

It will now be assumed that the wipers 18 have 45 reached a set of contacts 150 which lead to an idle repeater. The conductor 150' leading from this idle repeater will be open instead of being grounded. Accordingly, a circuit will be completed from ground through battery, winding of the private relay 154, closed off-normal contacts 152, back contact and armature 146, conductor 148, winding of the cut-through relay 161, conductor 116 and armature 138 and its front contact to ground. Relay 154 is not operated, as the current flow is not sufficient therefor, but relay 161 is so constructed as to operate over this circuit. Upon energization of relay 161, the circuit from the calling station 1 is extended over conductors 117 and 118, armatures 133 and 134 in engagement with their front contacts, and over wipers 18 and contacts 150 to the feed relay 23 of the repeater 14. 55

The feed relay 23 is now energized over the circuit to the calling station apparatus and at its armature 24 completes a circuit to the bypass resistance 25, the circuit extending from ground to battery through the winding of the relay 162 to the back contact and armature 164 of the cut-off relay 165 to armature 24 in engagement with its front contact, resistance 25 and armature 166 in engagement with its back contact to ground. 60

Line relay 162, cut-off relay 165 and motor magnet 168 control a rotary line switch 15 similar in construction to the rotary line switch 1 described in the above. Upon energization of the relay 162 over the circuit traced above, 65 70 75

ground is placed on the conductor 169 leading to the motor magnet 168 from the brush 171 if this brush is in engagement with a busy contact 172. It will be understood that ground is applied to the segment 172 as long as it is busy, or in other words, has been seized by some other rotary line switch. As in the previous case, the rotary line switch 15, is individual to the telegraph repeater relay 23.

10 In the event that ground is applied to the conductor 169 when brush 171 is on a busy segment 172, the rotary magnet 168 is energized and its armature opens its own circuit at the same time stepping the brushes 171 and 174 and 175 to the 15 succeeding steps of contacts 172, 176 and 177. As soon, however, as the brushes 171, 174 and 175 engage a set of contacts 172, 176 and 177 which are not busy, ground will no longer be obtained at 172 and an energizing circuit is then completed 20 from ground, through armature 178 of line relay 162, in engagement with its front contact, through the winding of the cut-off relay 165 and to the motor magnet 168 to battery and ground. The motor magnet 168 is so constructed that it 25 does not respond to this circuit, but the relay 165 is energized. As in the previous case, it will be noted, as long as ground is obtained on the conductor 169 from the bank contact 172, relay 165 will be shunted and not energized. Energization of relay 165 extends a circuit from the 30 armature 24 of the repeater relay 23 over armatures 164 and 166, in engagement with their front contacts, to the wipers 174 and 175 on bank contacts 176 and 177 extending as will now appear 35 to the next selector.

This circuit now extends over conductors 181 and 182 to armatures 183 and 184 (Figure 4), respectively, and their back contacts of a cut-through relay 185 and to the windings of a line 40 feed relay 186 of a second selector 16. The second selector 16, it will be noted, is similar in construction to the selector 8 described in detail above. As in that case, there is provided a line feed relay 186 which is periodically energized 45 and deenergized in accordance with the impulses received over the lines 181 and 182.

The line feed relay 186 is energized and at its armature 188 completes an obvious energizing circuit for the release relay 187 which is of the 50 slow-to-release type. Release relay 187, upon energization, moves its armature 190 into engagement with its front contact and extends ground to the trunk 180 connected to the bank contact 172, so that any other wiper 171 of any 55 other rotary line switch moving over this contact 172 will find ground thereon shunting its associated cut-off relay 165 and continuing the operation of its associated motor magnet 168.

The letter S will now be dialed. As the letter 60 S is dialed, the line feed relay 186 is periodically deenergized and energized. At the first deenergization of the line feed relay 186 in the dialing operation, a circuit is completed through the windings of the slow relay 191 and vertical magnet 192. The slow relay 191 is energized and will remain energized until the last of the group 65 of impulses representing the letter S is dialed. The vertical magnet 192 is energized to step the wiper 194 from one contact 191 to the succeeding 70 contact 197. At the first step of the wipers by the vertical magnet 192 the off-normal switch 198 closes its contacts.

It is assumed that seven impulses are transmitted when the letter S is dialed. Accordingly, 75 the vertical magnet 192 is energized seven times,

moving the wipers 194 step-by-step until they reach the seventh row of selector contacts on the selector 16.

Energization of the slow relay 191 operates its armature 193 to engage its front contact and a 5 circuit is completed through the winding of the private relay 199. Private relay 199 is energized and completes a locking circuit for itself.

At the end of the impulsive, relay 186 remains 10 energized sufficiently long to in turn deenergize slow relay 191. Deenergization of slow relay 191 completes a circuit for energizing rotary magnet 202. Energization of rotary magnet 202 prepares the wipers 194 for stepping over the contacts 197 and breaks the locking circuit of private 15 relay 199, deenergizing this relay. Deenergization of private relay 199, opens the energizing circuit of rotary magnet 202. Deenergization of rotary magnet 202 rotates the wipers into engagement with a contact 197. If the repeater 20 to which this contact is connected is busy, the rotary magnet 202 will be energized to rotate the wipers into engagement with the succeeding contact, as described in connection with selector 25 8. If, however, the repeater is idle, the cut-through relay 185 will be energized and the circuit from conductor 181 and 182 will be extended over armatures 183 and 184, and their respective front contacts, over wipers 195 and 196, and the contacts engaged therewith to repeater 12. 30

The selector repeater 12 combines the function of the selectors such as selector 8 and selector 16 and that of a repeater for repeating the next dial impulses over two conductors to a set of selector switches at the distant switching office. It will 35 be noted that up to this point connections between the rotary line switches and the selectors at various steps have been made over three conductors. Inasmuch as the apparatus thus far described, including the selector repeater, is all 40 located at one station, the use of three wires between the various apparatus is not objectionable. It will be clear, however, that in making connections to a remote station, the use of three wires would render the system entirely too costly. The 45 selector repeater is therefore arranged to repeat the next dialed impulses over a two wire system as will appear from the following description.

As will be clear from a comparison, the selector 50 part of the selector repeater 12 is essentially the same as the selectors 8 and 16. As in each of the previous selectors, there is the usual line relay 211, similar to the line relay 186 of selector 16, release relay 212 similar to the release relay 187, slow relay 213 similar to the slow relay 191, 55 cut-through relay 214 similar to the relay 199, stepping magnet 215 similar to the vertical stepping magnet 192 and a rotary magnet 216 similar to the rotary magnet 202, for rotating the wipers to engage the contacts opposite which they have been positioned. The repeater which makes up the remaining portion of the apparatus is provided with a tone relay 221, condenser cut-off relay 222, electro-polarized relay 223, and the bridging relay 224 which has two independent 60 windings.

Upon the connection of the brushes 195 and 196 with the contacts 197, the circuit from armature 24 of the repeater relay 23 is extended over the make before break contacts 231 and 232 to the windings of the line feed relay 211. Upon 70 energization of line feed relay 211, relay 212 is energized which at its armature 233 places ground on the release trunk 197 leading to the wiper 184.

The subscriber now dials the letter O comprising six impulses. As the letter O is dialed, the line feed relay 211 is periodically deenergized and reenergized. At the first deenergization of the line feed relay 211 in the dialing operation a circuit is established from ground over armature 234 in engagement with its back contact, armature 235 in engagement with its front contact, armature 236 and its back contact, armature 238 and its back contact and through the windings of the slow relay 213 and the vertical stepping magnet 215 to battery and ground.

The slow relay 213 is energized and will remain energized until the last impulse of the group of impulses representing the letter O is dialed. The vertical magnet 215 is energized to step the wipers 241, 242 and 243 from one level of contacts to the succeeding level of contacts. At the first step of the wipers by the vertical magnet 215 the off-normal switch 246 closes its contacts.

In the present case, it is assumed that six impulses are transmitted in the dialing of the letter O and accordingly the vertical magnet 215 is energized six times, moving the wipers six times until they reach the sixth level of contacts.

Energization of the slow relay 213 operates its armature 244 to engage its front contact and establishes a circuit from ground to the front contact and armature 233, armature 244 and its front contact to the contact of the off-normal switch 246, through the winding of the private relay 245, battery and ground. The private relay 245 upon energization will form a locking circuit for itself from ground through battery and the winding of the relay 245, through the closed contact of the off-normal switch 246, the front contact and armature 245' of the relay 245, armature 247 and the back contact of the rotary magnet 216 and over the armature 233 and its front contact to ground.

At the end of the impulsive, line feed relay 211 remains energized long enough to deenergize slow relay 213 which moves its armature 244 into engagement with its back contact and completes a circuit for rotary magnet 216 from ground to battery, through the winding of the rotary magnet 216, front contact and armature 251, back contact and armature 244 and front contact and armature 233 to ground. Rotary magnet 216 will energize over this circuit and operate to prepare the wipers for stepping over the contacts in the sixth level. In addition, the rotary magnet 216 moves its armature 247 away from its back contact and thereby opens the locking circuit of the relay 245 and deenergizing this relay. Deenergization of relay 245 opens the circuit of the rotary magnet 216 at armature 245'. Deenergization of rotary magnet 216 rotates the wipers into engagement with a set of contacts.

If the first bank contact is idle a circuit will be established from ground, through battery, through the winding of the relay 245, through the closed contacts of the off-normal switch 246 back contact and armature 253, through the winding of the relay 214, through armature 233 and front contact to ground. The relay 245 is not energized over this circuit but relay 214 is energized and operates its armature 238 to prepare the repeater circuit.

Relay 214 upon energization opens the energizing circuit of the slow relay 213 and completes an energizing circuit for the slow relay 222 from ground to battery to the winding of relay 222, front contact and armature 238, back contact and

armature 236, front contact and armature 235, back contact and armature 234 to ground.

As soon as the wipers 241 to 243 engage their contacts, a circuit is established over the two trunk conductors 261 and 262 to the line relay 263, Figure 5, at the remote station selector 28. This circuit extends from ground, through battery at the remote selector, to the upper winding of the relay 263, back contact and armature 264 of the break relay 265, conductor 262, wiper 242, armature 266 of relay 214 in engagement with its front contact, armature 267 and its back contact, lower winding of the relay 223, make-before-break contact 268, lower winding of the relay 224, over armature 269 and its front contact, over the wiper 241, conductor 261, armature 271, and its back contact and through the lower winding of the relay 263 to ground. The line relay 263 at the selector 28 will energize over this circuit and stand in readiness to receive the impulses which will be sent in by the repeater.

When the relay 224 energized, a circuit was established from ground, to battery, through the upper winding of the relay 223 and over the armature 272 in engagement with its front contact, to ground. The current now flows in both windings of relay 223, but these windings are opposed so that the relay is not operated.

When the subscriber dials the next character which in the present case is assumed to be numeral 8, the line feed relay 211 will momentarily release its armature 234 each time. Each time the line feed relay 211 deenergizes, a circuit is closed from ground through armature 234 in engagement with its back contact, armature 235 in engagement with its front contact, armature 236 and its back contact, armature 238 and its front contact, through the relay 222 to battery and ground. The relay 222 will energize over this circuit and since it is a slow acting relay, will maintain its armature in an operative position as long as the line relay 211 is responding to the dial impulses. When the relay 222 energizes, the upper condenser 275 is disconnected from the trunk, and at the same time the circuit to the lower winding of relay 223 and the lower winding of the relay 224 will be opened at armature 261. The circuit for the relay 263 now extends from the wiper 242 to armature 266 and its front contact, armature 267 and its front contact, armature 269 and its front contact, and the wiper 241. Each time the line relay 211 deenergizes, it will open the circuit of the line relay 263 at armature 269 and in this way, the dialing impulses are repeated over the trunk to the switches at the remote exchange which will respond to the repeated impulses and complete the connection in the usual manner.

If the trunk tested had been busy, the selector repeater would have started rotating in an attempt to find an idle trunk in the same manner as explained in connection with the selectors 8 and 16. The selector repeaters carry a private bank which is multiplied among all switches. This bank is not connected with the trunk but is used only to protect a trunk from intrusion after a selected repeater has seized it. The private bank contact is made busy over the circuit from the private wiper 243 on which ground is applied as soon as the trunk is busy and which thereupon shunts the private relay such as relay 245 preventing it from operating and permitting periodic energization of the rotary magnet as explained in connection with selectors 8 and 16.

The distinction of telephone selection over tel- 75

- egraph selection in the operation thus far described would be merely in the omission of the telegraph repeater apparatus 14, the rotary line switch 15 and second selector 16, the first selector 5 being directly connected to the repeater selector 12 in the case of a telephone selection and the telephone dialing impulses being directly applied to the repeater relay 211 which in turn repeats the impulses over the conductors 261 and 262.
- 10 The difference in the effect between telegraphic and telephonic connections on the selector repeater will be described following the complete description of a selection to a called party.

From this point, all impulses transmitted from 15 the transmitting station by the dialing operation are applied directly to the telegraph repeater relay 23 which in turn repeats these impulses to the line feed relay 211, the line feed relay 221 in turn again repeating impulses over the conductors 261 and 262.

It is now assumed that the next dialing operation transmits, as stated, eight impulses and the line relay 263, Figure 5, at the selector 28 in the remote exchange is energized eight successive times.

The selector 28, it will be noted, is an exact duplicate of the selectors 8 and 16. It comprises the line relay 263 which operates in response to the initial current over conductors 261 and 262 30 to energize the release relay 281. The release relay 281 upon energization operates its armatures 282 and 283 to engage their front contacts. Upon each deenergization of relay 263, a circuit is completed over armatures 284 and 285 through 35 the slow relay 286 and the vertical stepping magnet 287. Both the slow relay 286 and the vertical stepping magnet 287 are thus energized, the stepping magnet 287 functioning to step the brushes 297, 298 and 299 from level to level.

40 Upon receipt of the last of these impulses, the armature 284 remains on its front contact sufficiently long to permit relay 286 to deenergize, it being understood that during the impulsing, however, the intervals are not sufficient to permit such deenergization of relay 286. Upon deenergization of relay 286 an energizing circuit is completed for the private relay 296 over the contact of the closed off normal switch 288, the front contact and armature 289 of the relay 286 45 and the armature 282 and its front contact, to ground. Relay 296 upon energization, locks itself over armature 291 of the rotary magnet 292. Upon deenergization now of relay 286 as traced above, the rotary magnet 292 is energized 50 to move the wipers 297, 298, 299 to engage the first contacts on the eighth level.

Energization of rotary magnet 292 will also 55 open the locking circuit of the relay 296 which upon deenergization in turn opens the circuit 60 of the rotary magnet 292 at its armature 193. The usual circuits including the relay 296 and 265 in series will now be established, relay 296, however, not energizing over this circuit. This is the condition obtained if the contact over 65 which the wipers 297, 298 and 299 engage is not busy; that is, there is no ground on the trunk with which the wiper 297 engages. If there is such a busy condition there is ground on this trunk and this ground extends over the wiper 70 297 shunting out the relay 265 at armature 294 and preparing another energizing circuit for the relay 296 which upon energization reenergizes the rotary magnet 292 to step the wipers to the next set of contacts on the eighth level and this 75 operation continues until the wipers reach a set

of contacts on this level which are not busy at which time the series circuit including relays 296 and 265, as described above, is completed and relay 265 is energized extending the circuit from conductors 261 and 262 over the armatures 264 and 271 in engagement with their front contacts to the wipers 298 and 299 in engagement with the contacts of the next selector 37.

The next selector 37 is similar to the selector 28 and comprises the line feed relay 301, the 10 release relay 302, the slow relay 303, vertical magnet 304, rotary magnet 305, private relay 306, release magnet 307 and the cut through relay 308. As in the previous case, by operation of these relays, the wipers 311, 312 and 313 are 15 stepped up eight level in response to the eight impulses comprising the dialing code assumed in the present case and the wipers 311 to 313 are raised to the eighth level. At this time, the rotary magnet 305 is energized once, causing the 20 wipers to engage the first set of contacts on this level. If the contacts are not busy the wipers will remain in engagement therewith. If they are busy, the wipers continue to the next set of contacts and so on in the same level until a 25 set of contacts which are not busy are reached. The relay 308 thereupon is energized, extending the circuit from wipers 298 and 299 through to the wipers 312 and 313 and over conductors 315 and 316 to the line feed relay 43.

The numeral 5 will now be dialed. During this operation the line relay 43 (Figure 6) will be deenergized and reenergized five times. Prior to this dialing operation the relay 43 will be energized, moving its armature 321 into engagement with its front contact. This closes a circuit from ground to battery through the winding of relay 326, front contact and armature 327 to ground. Relay 326 is energized moving its armature 328 into engagement with its front contact and extending 30 ground over line 317 and moving its armature 329 into engagement with its front contact. Relay 326, being of the slow type, will remain energized during the transmission of the five dialing impulses. The first signal transmitted in the dialing operation will deenergize line relay 43, establishing a circuit from ground over armature 327 in engagement with its back contact, armature 329 in engagement with its front contact, contact 331 of the off-normal switch 332, through 35 the winding of the slow relay 333 and the vertical magnet 334, through battery to ground. The vertical magnet 334 will now be energized, stepping the wipers 336, 337 and 338 vertically. 40

This operation will be repeated five times, one 45 for each impulse, and the wipers will be stepped to the fifth level. After the fifth impulse, the line feed relay 43 will remain energized for a period long enough to permit relay 333 to become deenergized. Relay 333 when deenergized, 50 moves its armature 335 into engagement with its back contact and a circuit will be prepared from ground over armature 327 if and when in engagement with its back contact, armature 329 in engagement with its front contact, switch 55 contact 341 of the off-normal switch 332, armature 335 in engagement with its back contact, armature 407 in engagement with its back contact, armature 343 in engagement with its back contact, through the winding of rotary magnet 60 344, through battery to ground. Simultaneously with the first energization of the rotary magnet 344, the slow relay 345 will be energized over a circuit which is in parallel with the rotary magnet 344. The slow relay 345, when energized, will 65 70 75

move its armature 351 into engagement with its front contact, closing a shunt circuit around the armature 407 and making the energizing circuit of the rotary magnet 344 independent of the position of the armature 407.

The numeral 5 will now be dialed a second time. The first impulses transmitted during this dialing operation will close the circuit above prepared and will energize the rotary magnet 344 five times, rotating the wipers 336, 337 and 338 over the contacts.

Following the fifth energization of the rotary magnet 344, the wipers 337 and 338 engage the contacts shown connected to the conductors 5 and 6. The line feed relay 43 remains energized at the end of the impulsion and the rotary magnet 344 is deenergized. Similarly the energizing circuit for the slow rotary relay 345 is also opened at armature 321 of the line feed relay 43 and relay 345 deenergizes after an interval of time permitting its armatures to drop to their back position. An energizing circuit is thereupon completed from ground, to battery, through the winding of the cut-off relay 361, contact and wiper 336, make-before-break contact 353, armature 354 in engagement with its back contact, through the upper winding of the private relay 362, back contact and armature 363, front contact and armature 328 to ground.

Relay 362 energizes and at armature 365 completes a locking circuit for itself from ground through battery lower winding of relay 362, front contact and armature 365, front contact and armature 328 to ground. At armature 343, the circuit of the rotary magnet 344 is opened. This has no effect as the circuit of the rotary magnet was already open. At armature 366 a ground is established for the wiper 336 from ground over the armature 366 and its front contact 353 and wiper 336. The movement of armature 366 into engagement with its front contact operates the contact 353 to open the original energizing circuit of relay 362, which extended through its upper winding. At armature 366, a circuit is prepared for relay 342. At armature 351, the circuit leading from busy relay 339 is opened so as to prevent energization of the busy relay 339. At armature 373 a ringing circuit is established from ground through ringing generator 371, back contact and armature 372, front contact and armature 373, wiper 338, conductor 6, arm 398 of change over switch 376, Figure 8, condenser 378, selective ringing relay 379, back contact and armature 381 to ground. The selective ringing relay 379 is energized and its armature completes an obvious energizing circuit for the relay 382 which in turn at its armature completes an energizing circuit for the magnet 383. Magnet 383 upon energization operates the armature 384 and the change over switch 376 to switch the circuits extending over the lines 5 and 6 to the local telegraph equipment.

As a result of the operation of the change over switch 376 an energizing circuit is completed for the detector relay 342 from ground through battery and the upper winding of the detector relay 342, back contact and armature 385, front contact and armature 386, wiper 337, conductor 5, switch 389 in engagement with its lower contact, contact 392, polar relay 393, printer magnet 394, transmitter 395, switch 396, switch 397, switch member 398 in engagement with its lower contact, conductor 6, wiper 338, armature 373 and its front contact, armature 372 and its back contact, through the source 371, to ground. Detector

relay 342 is energized over this circuit and operates its armatures to engage their front contacts. At armature 387 a locking circuit is completed for the relay 342 from ground, through battery, lower winding of relay 342, armature 387 and 5 its front contact, front contact and armature 328 to ground. At armatures 372 and 385 and their front contacts, the upper and lower windings of relay 48 are extended over conductors 5 and 6 in series with the receiving printing magnet 384 and telegraph transmitter 385. At armature 372, the ringing circuit is opened.

Armature 51 of relay 45 is in a circuit which extends from the line 5 to the line 6 so that the movement of armature 51 into engagement with 15 its front contact will shunt the receiving apparatus at the called station. At armature 406, a circuit is prepared for the secondary of the transformer 46. Over this circuit code signals of alternating current will be transmitted in accordance with the operation of relay 48 as will now be described.

Omnigraph signalling

When the magnet 383 is energized, the change-over switch 376 is moved to its lowermost position and a circuit for the motor 424 is closed. Simultaneously with the energization of the magnet 383, the notched omnigraph disk 427 is released for rotation as will be described in detail hereinafter. As the disk 427 rotates, it alternately opens and closes the switch 396 thereby deenergizing and energizing relay 48. Deenergization and energization of relay 48 will move its armature 47 back and forth to make and break the 35 circuit which extends from the transformer 46 over the conductors 315 and 316 to the relay 435, Figure 4, the circuit extending from the line over wiper 241, through the winding of the relay 435, over the back contact and armature 436, back 40 contact and armature 267, front contact and armature 266, wiper 242 and back over the line. Energization of relay 435 moves its armature 437 into engagement with the front contact and closes an energizing circuit for relay 438 from ground, 45 through battery and winding of relay 438, front contact and armature 437 to ground. Relay 438 closes a locking circuit for itself from ground, through battery and winding of relay 438, armature 439 and its front contact, armature 233 and 50 its front contact to ground. Armature 236 of relay 438 opens the circuit which extends to relay 222. At armature 440, the relay 438 closes a circuit for shunting the armature 269 and its contact. This shunting circuit extends from the 55 conductor which leads to the armature 269 to the front contact of armature 440, over armature 440 to the conductor which leads to the front contact of the armature 269 and maintains the line 261 independent of operations of the relay 211 and 60 further maintains relay 43, Figure 6, energized in order to prevent restoration of the selectors during telegraph signalling.

The first alternating current impulse and all others are transmitted over the lines to the repeater 14, these lines being in multiple with relay 435.

The notches in disk 427 are so cut that operation of this disk will transmit to the calling station the message TSO-8855. This message is 70 sent immediately after the dialing of the last figure of the directory number and acts as a signal to the calling station and further as a check by which the calling station knows the identity of the station connected.

Transmission of telegraph signals

In this case, transmission of telegraph signals is obtained by alternate intervals of current and no current. Such operations will now be described and may be understood by reference to either Figure 2 or Figure 9.

Normally when telegraphic signals are not being transmitted and the two lines are connected for telegraphic purposes relay 23 at repeater 14 and relay 48 at repeater 42 are both energized. Relay 23 is energized over a circuit extending from ground, through battery, upper winding of relay 23, printer magnet 86, transmitter 87, lower winding of relay 23, to ground. The circuit for relay 48 extends from ground, through battery, through the upper winding of relay 48, printer magnet 394, transmitter 395, lower winding of relay 48 to ground. When the transmitter 87 at station 1 is operated to open the first-described circuit, relay 23 will be deenergized, moving its armature 24 into engagement with its back contact and thereby completing an alternating current circuit for the relay 45 this circuit extending from the source 31, over back contact and armature 24, over the line to armature 47 in engagement with its front contact through winding of relay 45 and back over the line to the source 31. Relay 45 is energized, moving its armature 51 into engagement with its front contact and thereby shunting out the printing magnet 394 and transmitter 395 of the station 2. This deenergizes the printing magnet 394 and accordingly the said magnet registers a "no current" impulse. The "no current" impulse transmitted from station 1 is thus registered as a "no current" impulse at station 2.

When the transmitter 87 at station 1 closes the circuit to transmit a "current" impulse, relay 23 is energized, moving its armature 24 into engagement with its front contact thereby breaking the alternating current circuit above described. This deenergizes relay 45 causing its armature 51 to move away from its front contact thereby removing the shunt from printer magnet 394 and printer 45 395. Printer magnet 394 then becomes energized and registers a current impulse. In this manner a "current" impulse transmitted from station 1 is registered as a "current" impulse at station 2.

In a similar manner, "current" impulse transmitted by transmitter 395 will be registered as "current" impulses by the printer magnet 86 and "no current" impulses transmitted from the transmitter 395 will be registered as "no current" impulses by the printer magnet 86.

Operation of transmitter 395 opens and closes the circuit of relay 48 which operates, whenever it is deenergized, to move its armature 47 into engagement with its back contact thereby establishing a circuit from the secondary of the transformer 46 to energize the relay 411. The relay 411, whenever it is energized, moves its armature into engagement with its front contact to short circuit the line to calling station 1 thereby establishing a condition of "no current" on the line to the printer magnet 86 at station 1.

It will be clear from the above description that direct current impulses transmitted from calling station 1 are translated into alternating current impulses at the repeater 14, retranslated into direct current impulses at the repeater 42 and received by the called station 2 in the form of direct current impulses. In the same manner, direct current impulses transmitted from called station 2 are translated into alternating current impulses at the repeater 42, retranslated into direct

current impulses at repeater 14 and received at calling station 1 in the form of direct current impulses.

Busy signals

In the above description it was assumed that the called party was not busy at the time when the calling party attempted to establish communication with it. It will now be assumed that the called party was busy.

Under this condition, as described above, the wiper 336 will have ground on it. A circuit will be established from grounded wiper 336, switch 353, armature 354 in engagement with its front contact (relay 345 not having had time to de-energize), back contact and armature 357, winding of busy relay 339, battery and ground. Busy relay 339 energizes and upon the release of relay 345 it closes a locking circuit for itself at its armature 363. This locking circuit extends from ground through battery, winding of relay 339, armature 357 and its back contact, switch 356, front contact and armature 363, front contact and armature 328, to ground. At armature 407, the energizing circuit of the rotary magnet 344 is opened so as to prevent accidental energization of this rotary magnet 344. At armature 409, a circuit is prepared for the secondary of the transformer 46. At armature 408 a busy circuit is established for the relay 48, from ground, through battery, switch 411, armature 408 and its front contact, lower winding of relay 48, to ground.

The busy device 410 is rotated in the direction of the arrow shown in Figure 6 and the switch 411 is alternately opened and closed thus alternately deenergizing and energizing the relay 48. As this relay 48 is alternately deenergized and energized, its armature 47 will move back and forth between its contacts. Whenever the armature 47 engages its back contact, telegraphic code signals of alternating current will flow from the secondary of the transformer 46 over armature 412 in engagement with its back contact (relay 345 being still deenergized), armature 409 in engagement with its front contact, armature 47 in engagement with its back contact, conductor 315, through the repeater apparatus 14, conductor 316 and back to the secondary of the transformer 46. The repeater 14 will translate these code currents into current-vs-shunt conditions in the line to the calling station to print the word "busy" at the calling station to indicate that the called station is busy. Restoration of the selectors will then take place in response to a release of the calling party's apparatus as will be described hereinafter.

It will be evident from the above description that the relay 23 of the repeater 14 responds to both dialing and telegraph codes transmitted from the calling station. During the transmission of dialing signals and before the circuit has been completed to the called party, relay 23 repeats only direct current signals to energize the relay 211 of the selector repeater 12. The circuit for these direct current signals extends from ground, through battery, the upper winding of relay 211 over the connections completed as shown in Figure 9, armature 24 in engagement with its front contact, resistance 25, back over the completed circuits, lower winding of relay 211, to ground. While these direct current signals are being transmitted the alternating current signals from source 31 are transmitted also but are ineffective because the wire to armature 47 of relay 48 is open at armatures 406, 409 and 75

612, the connection through the called party being incomplete. When, however, the connection to the called party is completed, the relays 48 and 342 are energized. Thereafter deenergization of relay 23, in response to telegraph code signals, will transmit alternating currents from source 31 and through armature 24 and its back contact and the completed circuits to energize relay 48.

10

Restoration

In order to restore the apparatus, the calling station restores the starting key 76. The relay 23 will be deenergized and this in turn will deenergize line feed relay 211. Deenergization of line feed relay 211 will result in deenergization of slow relay 212. Deenergization of slow relay 212 moves its armature 233 away from its back contact thereby breaking the locking circuit of relay 214 and closing an energizing circuit for the restoring magnet 445 from ground, through battery, winding of the restoring magnet 445, upper contact of the off-normal switch 246, back contact and armature 235, back contact and armature 234, to ground. Restoring magnet 445 energizes and moves the wipers 241, 242 and 243, back to their normal position. At the same time, the off-normal switch 246 is restored to its normal open position thereby breaking the circuit of the restoring magnet 445. Movement of the armature 233 out of engagement with its front contact removes the ground from the wiper 194, and release trunk 197'. Removal of ground from release trunk 197' results in deenergization of relay 185.

35 Deenergization of relay 185 closes a circuit for the release magnet 446 from ground, through battery, winding of release magnet 446, lower contact of off-normal switch 198, back contact and armature 447, back contact and armature 448, back contact and armature 188 to ground. Release magnet 446 energizes and restores the wipers 194, 195 and 196 to their normal positions. At the same time, off-normal switch 198 is restored to its normal open position, thereby deenergizing the release magnet 446. Deenergization of relay 212 also takes ground off conductor 180 opening the locking circuit of relay 165 and the locking circuit of relay 161. Deenergization of relay 161 closes the circuit of release magnet 450 from ground, through battery, winding of release magnet 450, lower contact of off-normal switch 153, back contact and armature 142, back contact and armature 141, back contact and armature 136 to ground. Release magnet 450 energizes and moves the wipers 18 back to their normal position. At the same time the off-normal switch 153 is restored to its normal open position thereby breaking the circuit of the release magnet 450. The circuit of the relay 108 is opened by relay 212.

Deenergization of line feed relay 212 also opens the locking circuit of relay 438 which in turn deenergizes and opens the shunt across armature 269. The restoration of wipers 241 and 242 by release magnet 445 opens the circuit of relay 43. Deenergization of relay 43 breaks the circuit of relay 326 at armature 327. Relay 326 deenergizes and moves its armature 328 away from its front contact, thereby removing the ground from conductor 317, and moves its armature 329 into engagement with its back contact, establishing a circuit for the release magnet 451. This circuit extends from ground, through battery, winding of release magnet 451, off-normal switch 332, back contact and armature 329, back contact and ar-

mature 327 to ground. Release magnet 451 energizes and restores the wipers 336, 337 and 338 to their normal positions. At the same time the off-normal switch 332 is restored to its normal open position thereby breaking the circuit of the release magnet 451.

Movement of armature 328 away from its front contact breaks the locking circuit of the relay 382 and the locking circuit of the relay 342 and these relays become deenergized. Taking ground off conductor 317 opens the locking circuit of relay 308 which in turn completes an energizing circuit for the release magnet 307 from ground, through battery, winding of the release magnet 307, off-normal switch 452, back contact and armature 453, back contact and armature 454, back contact and armature 455, to ground. The release magnet 307 energizes and restores the wipers 311 and 312 and 313 to their normal positions. At the same time the off-normal switch 452 returns to its normal open position thereby breaking the energizing circuit of the release magnet 307. Deenergization of relay 328 takes ground off wiper 297 and opens the locking circuit of relay 285 and deenergization of relay 285 in turn completes an energizing circuit for release magnet 456 from ground, through battery, winding of the release magnet 456, lower closed contact of off-normal switch 288, back contact and armature 283, back contact and armature 285, back contact and armature 284, to ground. Release magnet 456 energizes and restores the wipers 297, 298 and 299 to their normal position. At the same time the off-normal switch 288 is restored to its normal open position thereby deenergizing the release magnet 456.

In this manner the selecting apparatus at both exchanges are restored to normal under control from the calling station.

Details of omnigraph mechanism

The omnigraph mechanism illustrated in Figures 11 and 12 will now be described. Secured to the shaft 425 of the motor 424 is a worm 475. The worm 475 cooperates with a worm gear 476 which is secured to a shaft 426 which carries a friction clutch mechanism 478 and a notched disk 427. Secured to the notched disk 427 is a sleeve member 428 having two lugs 429 and 429'. The disk 427 is adapted to be restrained from rotating by an escapement tooth 430 which is secured to the armature 384 of the electromagnet 383. When the electromagnet 383 is energized, it attracts the armature 384 and moves it clockwise about its pivot 488 thereby moving the escapement tooth 430 out of the path of movement of the lug 429 and into the path of movement of the lug 429'. The disk 427 will then be free to rotate by reason of its frictional engagement with the shaft 426. It rotates through an angle of almost 360°; that is, until the lug 429' comes into engagement with the tooth 430. When the electromagnet 383 is deenergized, the armature 384 is moved back to its original position and the tooth 430 moves back out of the path of the lug 429' and into the path of the lug 429. The disk 427 will then be permitted to revolve through the small angle remaining to complete its revolution.

As the notched disk 427 rotates, the follower 477 moves into and out of the notches of the disk, thereby breaking and making the contacts of the switch 396. The notches in the disk are cut in accordance with a predetermined code, the disks at any given station being cut in accordance with the code representing the director number of 75

that station; thus, the disk at station 2 has notches cut in it to represent the message TSO 8855 as shown in Figure 8. The disk in Figure 7 is cut to transmit the directory number TMA 8833. The disk 427 may be made of adjustable parts and can be assembled into a complete disk in any desired manner such for instance as the construction shown in Reissue Patent 177 issued to Morse in 1843.

10 It will be understood that when the switch 376 is shifted by the starting key, the omnigraph 427 does not revolve since the magnet 383 is not energized.

Modified Final Connector

15 It will be noted that the final connector shown in Figures 1 and 6 was utilized for telegraph connection only. The apparatus of Figure 23 is adapted to be utilized either as a final connector for a telephone connection without the telegraph repeater or as a final connector for a telegraph connection with the telegraph repeater. The speaking circuit for telephone service is shown in heavy lines. For telegraph service, the telegraph repeater is switched in by operating the relay 572 that operation being effected by a preliminary dial signal of two figures as will now be described. Assuming the index for telegraph service to be 22, the total director number for telegraph service will be TSO 882255. Dialing TSO 30 88 will connect the calling station 1 to the contacts 502 and 503 shown in Figure 23.

When connections are completed from the calling station 1 to the contacts 502 and 503, the line relay 504 will be energized. Energization of line relay 504 establishes an energizing circuit for releases relay 505 from ground through battery, through windings of release relay 505, front contact and armature 506 to ground. Energization of release relay 505 moves armature 507 into engagement with its front contact, thereby placing ground on contact 501, and moving armature 508 into engagement with its front contact. The numeral 2 will then be dialed. As the dialing takes place at the calling station 1, the relay 504 is de-45 energized and energized alternately.

Upon the first deenergization of line relay 504, its armature 506 moves into engagement with its back contact establishing a circuit for the slow vertical relay 509 and the vertical magnet 510, from ground, through battery, winding of vertical magnet 510, winding of slow vertical relay 509, closed contact 511 of off-normal switch 512, front contact and armature 508, back contact and armature 506, to ground. Slow vertical relay 509 and vertical magnet 510 are energized. Vertical magnet 510 steps the wipers 515, 516 and 517, vertically. At the same time, the off-normal switch 512 moves to its upper position, breaking contact 511 and making contact 520 and 521. Due to the fact that slow vertical relay 509 has been energized and off-normal switch 512 has moved to close contact 520 by the first pulse, the second and subsequent energizations of vertical magnet 510 are by way of contact 520 and armature 522 and its front contact.

After the second impulse, relay 504 remains energized for a period long enough to permit slow vertical relay 509 to become deenergized thereby breaking the energizing circuit of the vertical magnet 510 at the armature 522 of the slow vertical relay 509. Armature 522 now having moved to its back contact prepares a circuit for the rotary magnet 525. The numeral 2 will now be dialed again. This will produce alternate de-energization and energization of line feed relay

504. When the line feed relay 504 is deenergized, its armature 506 moves into engagement with its back contact establishing an energizing circuit for the rotary magnet 525 from ground through battery, winding of rotary magnet 525, back contact and armature 526, back contact and armature 527, back contact and armature 522, contact 510 of off-normal switch 512, front contact and armature 508, back contact and armature 506 to ground. A parallel circuit is established for slow rotary relay 528, from ground through battery to winding of slow rotary relay 528, back contact and armature 527, back contact and armature 522, contact 520 of off-normal switch 512, front contact and armature 508, 10 back contact and armature 506 to ground. Energization of slow rotary relay 528 moves its armature 530 away from its back contact, thereby maintaining in an open condition, the alternating current circuit which might be controlled by the busy relay 532. At armature 534, a shunt circuit is completed around the points of armature 527 from ground through battery, through winding of slow rotary relay 528, armature 534 in engagement with its front contact armature 522 15 in engagement with its back contact, contact 520 of off-normal switch 512, armature 508 in engagement with its front contact, armature 506 in engagement with its back contact, to ground. At armature 536, a circuit is prepared for busy 30 relay 532. The rotary magnet 525 now rotates the wipers step by step as the dialing impulses are transmitted from the calling station. When the wiper 515 arrives at the contact 545, and the dialing impulses cease at that directory number and the line relay remains charged long enough to release the slow rotary relay 528 then the armature 536 of the relay 528 will close the change-over circuit and private relay 540 and detector test relay 541 will be energized, the circuit extending from ground through battery, 35 through upper winding of detector test relay 541, contact 545, wiper 515, contact 546, back contact and armature 536, winding of private relay 540, back contact and armature 547, front contact 40 and armature 507 to ground. At armature 549, a locking circuit is established for the private relay 540 from ground through battery through the light winding of private relay 540, front contact and armature 549, front contact and armature 507 to ground. At armature 526, the circuit of the rotary magnet 525 is broken, it being noted, however, that this circuit has already been broken at the armature 534. At armature 550, ground is placed on the wiper 515. At armature 552 any possible circuit for busy relay 532 is 55 opened.

Energization of detector test relay 541 moves its armature 556 into engagement with its front contact establishing a locking circuit for this relay from ground through battery, lower winding of relay 541, front contact and armature 556, contact 521 of off-normal switch 512, armature 559 in engagement with its front contact, to ground. At armature 560, a circuit is established 60 for detector holding relay 561 from ground, through battery, through winding of detector holding relay 561, through armature 560 in engagement with its front contact, to ground. Detector holding relay 561 energizes and establishes 65 a holding circuit for itself at armature 562. This circuit extends from ground through battery to winding of relay 561, front contact and armature 562, front contact and armature 507, to ground. At armature 563, a ringing circuit extending from 70 75

the one hundred cycle source 565 is prepared. At armature 566 a circuit is prepared for the busy code omnigraph 570. This circuit, however, is not effective because the busy relay 532 is not energized at this time. At armature 571, a circuit is established for the repeater switching relay 572, from ground through battery to the winding of relay 572, front contact and armature 571, contact and armature 507, to ground.

10 Energization of the detector test relay 541 completes an energizing circuit for the restoring magnet 558 from ground through battery through winding of restoring magnet 558, contact 521 of off-normal switch 512, armature 559 in engagement with its front contact, to ground. Operation of the restoring magnet 558 restores to normal the wipers 515, 516 and 517. The off-normal switch 512 moves to its normal position as shown in Figure 23, breaking the circuit of the restoring magnet 558 at contact 521 and breaking the holding circuit of the detector test relay 541 at contacts 521. Detector test relay 541 deenergizes but repeater switch relay 572 and detector holding relay 561 remain energized through their locking circuit. The line feed relay 504 is held energized by the calling station 1 and the release relay 505 is held energized by the line feed relay 504. The calling station now dials the remaining figures 55.

20 30 The vertical magnet 510 is energized by the first series of these impulses to step the wipers 516 and 517 to the fifth level and the rotary magnet 525 is energized by the second series of these impulses to step the wipers 516 and 517 across to the fifth contacts in the fifth rows. The operation is exactly the same as described in connection with the dialing 22 described above.

40 Following this operation, a ringing current circuit is established through the relay 379 of the called party. This circuit is from ground through one hundred cycle alternating current source 565, front contact and armature 563, back contact and armature 575, front contact and armature 548, wiper 517, conductor 6, Figure 8, switch member 398, condenser 378, relay 379, back contact and armature 381 to ground. Relay 379 is energized completing a circuit for relay 382 which in turn completes a circuit for magnet 383.

50 Magnet 383 operates the change over switch 376 connecting conductors 5 and 6 together through printer magnet 394 and transmitter 395 as previously described.

55 As a result of this connection, the light winding of detector relay 555 is energized from ground through battery to the light winding of detector relay 555, armature 580 in engagement with its back contact, armature 554 in engagement with its front contact, wiper 516, contact in engagement with wiper 516, conductor 6, switch member 398 in engagement with its lower contact, switch member 391 polar relay 393, printer magnet 394, transmitter 395, contact 396, contact 397, switch 398 in engagement with its lower contact, conductor 5, wiper 517 armature 548 in engagement with its contact, armature 575 in engagement with its front contact, armature 563 in engagement with its lower contact source 565 to ground. The detector relay 555 is energized and locks itself through armature 581, the locking circuit extending from ground through battery through the heavy winding of detector relay 555 armature 581 in engagement with its front contact, armature 507 in engagement with its front contact to ground. At armature 575, the

55 circuit carrying the ringing current is broken, at armatures 575 and 580 the called party's line is switched to the back bridge relay 585. At armature 586 a circuit is prepared for the source 599 of alternating current of eleven hundred cycles. The back bridge relay 585 responds to telegraph codes transmitted by the called party and translates these codes into alternating current signals over the line to the calling party. The circuit extends from ground through battery through upper winding of back bridge relay 585 through armature 591 in engagement with its front contact, armature 575 in engagement with its front contact, armature 548 in engagement with its front contact, wiper 517, conductor 6, switch 15 member 398 in engagement with its lower contact, contact 397, omnigraph contact 396, transmitter 395, printing magnet 394, polar relay 393, contact 392, switch member 389 in engagement with its lower contact, line 5, armature 554 in 20 engagement with its front contact, armature 580 in engagement with its front contact, armature 592 in engagement with its front contact, lower winding of back bridge relay 585 to ground. Relay 595 responds to alternating current impulses 25 transmitted by the calling party to short circuit the apparatus of the called party.

Busy signals

It will now be assumed that the called party 30 is busy when the rotary magnet 525 moves the wipers 516 and 517 into engagement with the contacts leading to the called party. Under this condition, ground will appear on the wire 514 and wiper 515 and an energizing circuit will be 35 established for the busy relay 532 from ground, through battery, winding of the busy relay 532, armature 552 in engagement with its back contact, armature 536 in engagement with its front contact make-before-break switch 546, to ground 40 at wiper 515. Slow rotary relay 528 is deenergized and a locking circuit is established for the busy relay 532 from ground through battery, through winding of relay 532, armature 552 in engagement with its back contact, armature 547 45 in engagement with its front contact, armature 507 in engagement with its front contact, to ground. At armature 597 a circuit is established for the back bridge relay 585 from ground, through battery, upper winding of the back bridge 50 relay 585, armature 591 in engagement with its front contact, armature 597 in engagement with its front contact, armature 566 in engagement with its front contact, switch 598 of omnigraph 55 570, to ground.

The omnigraph 570 which rotates continuously will operate the make and break switch 598 which in turn will energize and deenergize the back bridge relay 585 to transmit to the calling station the word "busy" in code. This word is 60 repeated until the calling station releases the connection.

In the above, the telegraph operation of the final connector has been described. In the case of a telephone selection, the dial numbers 22 are 65 not transmitted and accordingly detector test relay 541 is not energized and accordingly detector holding relay 561 will not be energized. Due to the fact that detector holding relay 561 is not energized repeater switching relay 572 is not energized. Ringing current will be applied from the sixteen cycle alternator 599 over back contact and armature 563 to operate the telephone ringer as will be described in connection with figure 24. Busy signals for telephony will be supplied from 75

the busy tone device 600 over back contact and armature 566.

Operation for telephony

- 5 For telephonic communication over the system shown in Figure 1 the party at station 1 lifts the receiver and dials SO-8644. Dialing SO-86 connects calling station 1 through line switch 7, selector 8, selector repeater 12, selector 28, selector 10 37, to final connector 39, it being noted that repeaters 14 and 42 are not included in these connections.

The operations which take place when the numerals 4-4 are dialed will now be described, 15 reference being made to Figure 24 which shows the final connector 39 for telephone communication.

When connections are established between calling station 1 and contacts 626 and 627, the 20 line relay 628 will be energized. Energization of line relay 628 establishes an energizing circuit for release relay 629 from ground, through battery, winding of release relay 629, front contact and armature 630, to ground. Energization of 25 release relay 629 moves armature 631 into engagement with its front contact, thereby placing ground on contact 625, and moves armature 632 into engagement with its front contact thereby preparing a circuit for the vertical magnet 633. 30 As the dialing of the tens numeral 4 takes place, the line relay 628 will be alternately deenergized and energized.

Upon the first deenergization of the line relay 628, its armature 630 moves into engagement with 35 its back contact, establishing an energizing circuit for the slow vertical relay 634 in series with the vertical magnet 633, from ground, through battery, winding of vertical magnet 633, winding of slow vertical relay 634, contact 635 of off-normal switch 636, front contact and armature 632, back contact and armature 630, to ground. Vertical magnet 633 steps the wipers 640, 641 and 40 642 vertically. At the same time, off-normal switch 636 moves to its upper position breaking 45 the contact at 635 and making contact at 643 and 644. Due to the fact that slow vertical relay 634 has been energized and off-normal switch 636 has moved to make contact at 644, second and 50 subsequent energizations of vertical magnet 633 have been by way of front contact and armature 645 and contact 644. The vertical stepping magnet 633 now steps the wipers 640, 641 and 642 vertically step by step as the dialing impulses are transmitted from the calling station 1.

55 After the fourth impulse, the line relay 628 remains energized long enough to permit slow vertical relay 634 to become deenergized. De-energization of slow vertical relay 634 moves its armature 645 into engagement with its back contact 60 thereby opening the circuit of the vertical magnet 633 already open at relay 628 and preparing a circuit for the rotary magnet 648. The dialing of the units numeral 4 now takes place, alternately deenergizing and energizing the line 65 relay 628.

Upon the first deenergization of the line relay 628 its armature 630 moves into engagement with its back contact establishing an energizing circuit for the rotary magnet 648 from ground, through 70 battery, winding of rotary magnet 648, back contact and armature 649, back contact and armature 650, back contact and armature 645, contact 644 of off-normal switch 636, front contact and armature 632, back contact and armature 630, to ground. A parallel circuit is established for the

slow rotary relay 652 from ground, through battery, winding of the slow rotary relay 652, back contact and armature 650, back contact and armature 645, contact 644 of off-normal switch 636, front contact and armature 632, back contact and armature 630, to ground. Energization of slow rotary relay 652 moves armature 653 into engagement with its front contact thereby closing a shunt circuit for armature 650 from ground, through battery, winding of slow rotary relay 652, 10 armature 653 in engagement with its front contact, armature 645 in engagement with its back contact, contact 644 of off-normal switch 636, front contact and armature 632, back contact and armature 630, to ground. The rotary magnet 648 15 now rotates the wipers 640, 641 and 642 over the contacts step by step as the dialing impulses are transmitted from the calling station 1.

Following the fourth energization of the rotary magnet 648 the wipers 640 and 641 engage the 20 contacts connected to the conductors 5 and 6, respectively. The line relay 628 remains energized at the end of the impulsive and at armature 630 opens the circuit leading to the rotary magnet 648 and slow rotary relay 652. The 25 rotary magnet 648 is immediately deenergized whereas the slow rotary relay 652 is deenergized after a short interval.

Deenergization of slow rotary relay 652 moves its armature 655 into engagement with its back 30 contact, establishing an energizing circuit for the private relay 656 from ground, through battery, cut-off relay 361, Figure 6, wiper 642, make-before-break switch 657, armature 655 in engagement with its back contact, upper winding of 35 private relay 656, armature 658 in engagement with its back contact, armature 631 in engagement with its front contact, to ground.

Private relay 656 energizes initially and at 40 armature 660 completes a final energizing circuit for itself from ground, through battery, lower winding of private relay 656, front contact and armature 660, front contact and armature 631, to ground. At armature 649 the circuit of the rotary magnet 648 is opened. This has no effect 45 as the circuit of the rotary magnet was already open. At armature 661 a ground circuit is established for the wiper 642 from ground, over the armature 661 in engagement with its front contact to wiper 642. Movement of armature 661 50 into engagement with its front contact operates the make-before-break switch 657 to open the original energizing circuit of private relay 656 which circuit extended through the upper winding of the private relay 656. At armature 662 55 a circuit is prepared for relay 665. At armature 666 the circuit of the busy relay 667 is opened so as to prevent energization of the busy relay.

At armature 670, a ringing circuit is established from ground, through ringing generator 672, back contact and armature 674, front contact and armature 670, wiper 640, conductor 5, arm 389 in engagement with its upper contact, contact 675, conductor 676, condenser 677, ringer 678, conductor 679, condenser 680, conductor 681, switch arm 398 in engagement with its upper contact, conductor 6, wiper 641, armature 662 in engagement with its front contact, armature 684 in engagement with its back contact, upper 70 winding of detector relay 665, through battery, to ground.

The 16 cycle current supplied by the ringing generator 672 operates the ringer 678 but does not affect the relay 379 because the condenser 378 is designed to prevent large currents of 75

cycle from passing and the relay 378 is tuned for 100 cycles.

When the party at the called station responds by lifting the receiver 685 from the hook the switch arm 686 moves into engagement with its contact 687 establishing a direct current energizing circuit for the detector relay 688. This circuit extends from ground, through battery, upper winding of detector relay 685, armature 684 in engagement with its back contact, armature 682 in engagement with its front contact, wiper 641, conductor 6, switch arm 388 in engagement with its upper contact, conductor 681, relay 688, conductor 679, induction coil 689, contact 687, switch arm 686, microphone 690, contact 675, switch arm 389 in engagement with its upper contact, conductor 5, wiper 640, armature 670 in engagement with its front contact, armature 674 in engagement with its back contact, ringing current generator 672, to ground. Detector relay 685 energizes and at armature 682 completes a locking circuit for itself extending from ground, through battery, lower winding of the detector relay 685, armature 692 in engagement with its front contact, armature 631 in engagement with its front contact, to ground.

Energization of detector relay 685 moves its armatures 674 and 684 out of engagement with their back contacts, breaking the ringing circuit, and into engagement with its front contacts, completing a circuit for reversing relay 695. This circuit extends from ground, through battery, upper winding of relay 685, front contact and armature 684, front contact and armature 682, wiper 641, conductor 6, switch arm 388 in engagement with its upper contact, conductor 681, relay 688, conductor 679, induction coil 689, contact 687, switch arm 686, microphone 690, contact 675, switch arm 389 in engagement with its upper contact, conductor 5, wiper 640, armature 670 in engagement with its front contact, armature 674 in engagement with its front contact, lower winding of reversing relay 695, to ground. The reversing relay 695 is energized and moves its armatures 696 and 697 into engagement with their front contacts, operating make-before-break switches 698 and 699 to reverse the polarity upon the trunks leading back to the selector 37 for a purpose to be described hereinafter.

50   *Busy signals*

It will now be assumed that the called party is busy when the rotary magnet 525 moves the wipers 640 and 641 into engagement with the contacts leading to the called party. Under this condition, ground will appear on the wiper 642 and an energizing circuit for the busy relay 667 will be established from ground through battery, winding of busy relay 667, armature 666 in engagement with its back contact, armature 655 in engagement with its front contact, make-before-break switch 657, to grounded wiper 642. Slow rotary relay 662 is deenergized permitting make-before-break switch 701 to close thereby establishing a locking circuit for busy relay 667 from ground, through battery, winding of busy relay 667, armature 666 in engagement with its back contact, make-before-break switch 701, armature 658 in engagement with its front contact, armature 631 in engagement with its front contact, to ground.

Energization of busy relay 667 moves its armature 702 into engagement with its front contact extending a circuit from busy tone device 703 over the line to the calling station.

Guard signals

When two sets, telegraph and telephone, are served by a single line, means is provided to indicate when either set is in use, thereby warning persons against the use of the other set at the same time. This indicating means is shown in Figure 7 in the form of lamps 85 and 97.

When the telephone hook is lifted a circuit is established for the lamp which is located at the telegraph set. This circuit extends from ground through battery, lamp 97, conductor 98, switch arm 94, to ground. The lamp 97 then warns persons intending to use the telegraph set that the telephone set is in use. Instead of lamp 97 a lock 15 may be employed at the telegraph set for preventing operation of the starting key 78 while the telephone set is in use.

When the change-over switch 74 is operated, a circuit is established for the lamp 85 which is located at the telephone set. This circuit extends from ground, through battery, lamp 85, switch arm 71 in engagement with its lower contact, to ground. The lamp 85 then warns persons intending to use the telephone set that the telegraph set is in use. Instead of lamp 85, a lock 25 may be employed at the telephone set for preventing operations of the hook switch 63 while the telephone set is in operation.

It will be noted that in Figure 7 the lamp-control contacts have been added to the hook switch 63 of the telephone set. In installations where a telegraph set is to be added to an already existing telephone set a relay 688, Figure 8, may be provided in the telegraph set to control the circuit of the lamp 97. By using relay 688 instead of auxiliary contacts at the hook switch of the telephone set, modification of the telephone set becomes unnecessary.

40   *Metering*

One form of metering apparatus for registering the calls made by a station is shown in Figure 18. In this figure, electromagnet 725 controls the metering apparatus which is operated when the called station responds to a call for telephone communication and the electromagnet 726 controls the metering apparatus which is operated when the called station responds to a call for telegraph communication.

When a telephone connection is made, the polar relay 121 is energized, as will now be described. It will be recalled that when the called party responds to a telephone call, the relay 695 of the final connector 39, Figure 24, is energized and moves its armatures 696 and 697 into engagement with their front contacts operating make-before-break switches 698 and 699 to reverse the polarity upon the trunk leading back to the wipers 242 and 241, Figure 4. Prior to this reversal of polarity of the wipers 242 and 241, the circuits of the lower winding of relay 223 extended from wiper 242, over armature 266 in engagement with its front contact, armature 222 in engagement with its back contact armature 438 in engagement with its back contact, lower winding of relay 223, make-before-break switch 268, lower winding of relay 224, armature 269 in engagement with its front contact, to wiper 241. The circuit for the upper winding of relay 223 extended from ground, through battery, upper winding of relay 223, armature 272 in engagement with its front contact, to ground. The direction of flow of current in the lower winding of relay 223 was such as to counteract the effect of the upper winding and the relay 75

223 remained deenergized. Upon the reversal of polarity of wipers 242 and 241, as above described, the direction of flow of current through the lower winding of relay 223 will be reversed, and, since 5 the direction of flow of current through the upper winding remains the same, the effect of the two windings will be cumulative and relay 223 will be energized. Energization of relay 223 establishes an energizing circuit for the relay 221 from 10 ground through battery, winding of relay 221, armature 770 in engagement with its front contact, to ground. Energization of relay 221 reverses the current from relay 211 and this results in the reversal of current on the wipers 114 Figure 18, and through polar relay 727 which is then 15 energized.

Energization of polar relay 727 establishes an energizing circuit for magnet 725 from ground, through battery, winding of magnet 725, contact 20 128, armature 729, to ground. Magnet 725 energizes, rotating its armature 730 about its pivot 731, thereby operating pawl 732 which is in engagement with a tooth of ratchet wheel 733 to 25 rotate the ratchet wheel counterclockwise one step. This registers the call on the meter. Operation of armature 730 depresses switch 735 to establish a locking circuit for magnet 725 from ground, through battery, winding of magnet 725, resistance 736, closed contact 737, front contact 30 and armature 131, wiper 114, contact 115, Figure 3, front contact and armature 140, conductor 139, wiper 18, contact 150, conductor 150', front contact and armature 170, wiper 171, contact 172, conductor 180, front contact and armature 189, 35 wiper 194, contact 197, conductor 197', armature 233 and its grounded front contact, to ground.

Operation of switch 735 also closes its contact 40 740 thereby shunting the polar relay 727 and the magnet 741. Upon the release of the connection 45 the removal of ground from the release trunk de-energizes the magnet 725.

When a telegraph call has been made and the called party responds there is no reversal of current as in the case of a telephone call and the 45 polar relay 727 is not energized. Instead the magnet 741 operates its armature at each dial impulse and again operates its armature at each impulse of the omnigraph signal from the called station or from the omnigraph switch 396 of the 50 called station. All of these signals step the ratchet wheel 745 but not sufficiently to close the circuit of the magnet 726. If the calling telegraph station permits the busy message to repeat unreasonably, a connection will be registered. Obviously, the calling party should not 55 permit the busy message to repeat unreasonably.

When the telegraphic communication begins, the magnet 741 will continually step the wheel 745 until the circuit of the magnet 726 is closed 60 at switch 746. Energization of magnet 726 operates its armature 747 counterclockwise about its pivot 748 thereby moving pawl 749 to rotate the ratchet wheel 750 in the direction of the arrow. Rotation of wheel 750 registers the telegraph 65 call. The counterclockwise rotation of the armature 747 operates switch 753 to open at contact 754 the shunt around the resistance 755. This introduces the resistance 755 into the circuit of magnet 726 and thus reduces the current flowing 70 through the magnet winding. The operation of the switch 753 closes the contact at 757 thereby shunting both polar relay 727 and magnet 741. The ratchet wheel 745 is detained by the holding dog 760 which is controlled by the magnet 761. 75 The magnet 761 is energized over a circuit which

extends from ground, through battery, winding of magnet 761, front contact and armature 131, wiper 114, contact 115, front contact and armature 40, conductor 139, wiper 18, contact 150, conductor 150', front contact and armature 170, wiper 171, contact 172, conductor 180, front contact and armature 189, wiper 194, contact 197, conductor 197', armature 233 and its grounded front contact to ground. This circuit is broken when the connection is released thus deenergizing magnet 10 761 and releasing the wheel 745 which returns to normal by its spring 762. Preferably the wheel 745 is so adjusted that the response of the called station will record a connection. The calling station should release the connection by operating 15 the starting key as soon as the word "busy" has been received once, to prevent the meter from recording.

The number of teeth in the wheel 745 may be predetermined, say one hundred, and for each 20 called station the number of steps of the wheel will be predetermined by the directory number of the station. This number may be from twenty to seventy depending upon the number of impulses which the dial is required to make in calling that station. To this will be added a predetermined number of impulses by the omnigraph directory number signal from the called station and should this total be not enough to close the circuit of the telegraph meter magnet 726, additional notches for sending signals may be provided in the omnigraph disk as shown in Figure 17 and thus the operation of the meter may be assured by the response of the omnigraph. The additional notches will operate the printer of the 25 calling station, but they may be of such nature as to send only non-printing signals.

A modification of the metering system is shown in Figure 19 in which two slow relays 779 and 780 and a telegraph detector relay 781 are employed. When the calling station has dialed a figure such as TSO-8855, the ratchet wheel 745' will have taken seven steps, but it requires further steps to close the circuit of the telegraph meter magnet 726'. In a system using this 40 method of metering, the omnigraph disk will be cut as shown in Figure 21 and the first response will be the transmission of a sufficient number of break signals, each of which will step the wheel 745' and the last of which will operate the magnet 50 726'. The omnigraph disk then follows with the directory number.

Time limit device

In Figure 7, a switch 92 is shown in series with 55 the magnet 91. Switch 92 is a time limit switch and will open in case the calling station permits the starting key 75 to remain under control of magnet 91 without transmission of telegraph signals for a predetermined length of time. The 60 opening of switch 92 deenergizes magnet 91 and releases starting key 75 and returns change-over switch 74 to normal and the connection at the central office is broken. The mechanical details of the time limit switch are shown in Figures 13, 65 14 and 15.

The motor 809 has on its shaft 810 a worm 811 which cooperates with a worm gear 812 secured to the shaft 813. Secured to the shaft 813 is a worm 814 and cooperating with this worm is a 70 follower 815 which is an integral part of a striker arm 816. Striker arm 816 is in the form of a bell crank lever pivoted at 817 to a support 818 which in turn is pivoted at 819.

The striker arm 816 is adapted to swing in a 75

horizontal plane about its pivot 817 and is adapted to swing in a vertical plane about the pivot 818. The motor 809 turns the worm 814 continuously through the gear connections shown and the striker arm 816 is drawn downwardly by a spring 820 which in turn tends to cause the follower 815 to engage with the worm 814.

Normally, however, the operating key 75 acts as a stop for the striker arm 816 and prevents engagement between the follower and the worm. When the station is called, the starting key 75 is not operated and the time limit device does not operate. When the station is calling, however, the movement of the starting lever 75 permits the striker arm 816 to drop so that the follower 815 engages with the worm 814 and rotation of the worm 814 drives the striker arm 816 slowly towards the contacts 825. When the lug 826 on the striker arm 816 engages the contacts 825, the circuit through the magnet 81 is opened. At each operation of any key 830 of the transmitter 87, the rocker 831 will lift the striker arm 816 momentarily thereby disengaging the follower from the worm and permitting the spring 832 to restore the striker arm to the position shown in Figure 14. Should no key be operated for a predetermined length of time, the striker arm will open the contact 825 thereby deenergizing the magnet 81. The contacts 825 are the contacts 82 in Fig. 7.

Remote selection test

The omnigraph at the called station notifies the calling station that the central office selection has been effected properly and that the motor at the called station has been started. Had the motor not started, the omnigraph signal would not have been returned and had the central office selection been in error a wrong line 40 would have been obtained and the omnigraph of that line would have returned some number other than the number dialed.

In addition to the omnigraph signal, a remote selection signal apparatus is provided which tests 45 the proper operation of the called station and determines whether the apparatus at the called station is in condition to properly receive and interpret the telegraph signals. This remote selection test apparatus is shown in detail in Figure 16.

50 Referring to Figure 16, two pairs of contacts are shown. One pair of contacts 850 is arranged to be operated by the shift mechanism of the printer. To this end, the contact carrying arm 851 is arranged to be elevated by the shaft 852 of the platen 853 when the platen is shifted to the upper case position as shown by the dotted lines in Figure 16. The other pair of contacts 855 is so disposed as to be operated by one of the pull bars of the printer. To this end, the contact carrying arm 856 is arranged in the path of movement of the pull bar 857. The pull bar 857 is operated when the letter M is transmitted from the calling station.

The circuit through the two pairs of contacts 65 850 and 855 will be open only when the signal "shift M" is transmitted from the calling station. When the printer at the called station is in the shifted position any signal may be sent other than "M" without opening the test circuit. 70 When the printer is not shifted, the signal for "M" may be sent without opening the test circuit. There is a test device of the type shown in Figure 16 at the calling station and a similar one at the called station as shown at 73 and 84 in Figure 7 and at 381 and 392 in Figure 8.

When the party at the calling station desires to test the operating condition of the called station the signal "shift M" is sent. The signal "shift" operates printers at both stations to shift the platen into the upper case position. The signal "M" operates the pull bar 857 at both stations and breaks the line wire momentarily which sends an unshift signal. This unshift signal restores both platens to the lower case position without operating the unshift key of the transmitter 87.

Thus when either party holds closed the key 860 and sends the code "shift M" and notices that the platen unshifts automatically he is advised that the called station apparatus is in condition to properly receive and transmit telegraph messages.

For operating the pull bar 857, a plurality of permutation bars 865 are provided. Each of these bars has notches 866. When the code 20 signals for the letter M are received, the permutation bars are operated so that certain notches are in alignment. Spring 867 then pulls the bar 857 into these aligned notches and an operating member 868 then moves upwardly to 25 the dotted line position shown in Figure 16. During this upward movement, lug 869 of operating member 868 engages within notch 870 on pull bar 857 and the bar 857 is operated vertically upward. The bar 857 is connected with a type bar carrying the letter M so that upward movement of bar 857 operates the type bar but not to print the letter M and, as stated above, during this upward movement of bar 857 switch arm 856 is moved to its dotted line position breaking the engagement 35 between the contacts 855.

Combined telephone selector and telegraph selector repeater

The apparatus of Figure 20 is adapted to be 40 utilized either as a selector for a telephone connection without the telegraph repeater or as a selector for a telegraph connection with the telegraph repeater. The speaking circuit for telephone service is shown in heavy lines. For telegraph service, the telegraph repeater is switched in by operating the relay 900, such operation being effected by a preliminary dial signal as will be described.

It will be assumed that calling station 1 desires 50 to establish telegraph communication with called station 2, the directory number for telegraph service of station 2 being TSO-8855. The party at station 1 operates the starting key 75. Rotary line switch 7 will operate as described above to connect station 1 with an idle selector. Assuming the selector shown in Figure 20 to have been selected, wipers 114 will be in engagement with contacts 902, 903 and 904.

As soon as connections are completed from the calling station 1 to the contacts 902, 903 and 904, the line relay 905 will be energized. Energization of line relay 905 establishes an energizing circuit for release relay 907 from ground through battery, through winding of release relay 907, front contact and armature 906 to ground. Energization of release relay 907 moves its armature 908 into engagement with its front contact thereby placing ground on contact 904 and moves armature 909 into engagement with its front contact 65 preparing a circuit for the vertical magnet 810 and slow vertical relay 811. The letter T will then be dialed.

As the dialing of the letter T takes place at the calling station 1, the line relay 905 is deenergized 75

and energized alternately. Upon the first deenergization of line relay 905, its armature 906 moves into engagement with its back contact establishing a circuit for the slow vertical relay 911 and the vertical magnet 910 in series. This circuit extends from ground through battery, winding of vertical magnet 910, winding of slow vertical relay 911, front contact and armature 909, back contact and armature 912, back contact 10 and armature 906 to ground. Vertical magnet 910 and slow vertical relay 911 are energized. Vertical magnet 910 steps the wipers 915, 916 and 917 vertically. At the same time, the off-normal switch 920 moves to its upper position, closing its contacts 921 and 922. Closure of contact 921 establishes an energizing circuit for the private relay 925. This circuit extends from ground, through battery, winding of private relay 925, contact 921 of off-normal switch 920, front contact and armature 927 of slow vertical relay 911, armature 908 in engagement with its front contact, to ground. Energization of the private relay 925 completes a locking circuit for itself at its armature 928. This locking circuit extends from ground, through battery, winding of private relay 925, contact 921 of off-normal switch 920, back contact and armature 928 of rotary magnet 930, armature 928 and its front contact, to ground. Energization of private relay 925 also moves its armature 931 into engagement with its front contact preparing a circuit for the rotary magnet 930.

As the eight impulses for the letter T are received by the line relay 905, the vertical magnet 910 is energized eight times stepping the wipers 915, 916 and 917 to the eighth level. During the receipt of these eight impulses, the slow vertical relay 911 remains energized, holding its armature 927 in engagement with its front contact. After the eighth impulse, the line relay 905 remains energized for a period long enough to deenergize the slow vertical relay 911. The deenergization of this slow vertical relay 911 moves its armature 927 into engagement with its back contact completing the circuit for the rotary magnet 930. This circuit extends from ground, through battery, through winding of rotary magnet 930, front contact and armature 931, back contact and armature 927, armature 908 and its front contact, to ground. Rotary magnet 930 energizes and rotates the wipers 915, 916 and 917 to the first set of contacts in the eighth level and moves its armature 929 away from its back contact thereby breaking the locking circuit of the private relay 925. Deenergization of the private relay 925 moves its armature 931 away from its front contact thereby interrupting the energizing circuit of the rotary magnet 930.

Wipers 915, 916, and 917 are now engaged with contacts 935, 936 and 937, respectively, and an energizing circuit for relay 945 is established. This circuit extends from ground, through battery, through winding of private relay 925, contact 921 of off-normal switch 920, back contact and armature 929, back contact and armature 946, wiper 917, contact 937, conductor 947, and upper winding of relay 945, to ground. Energization of relay 945 moves its armature 948 into engagement with its front contact establishing an energizing circuit for the relay 950 from ground, through battery, winding of relay 950 and armature 948 in engagement with its front contact, to ground. At armature 951, a circuit is completed for the relay 945 and the release magnet 952 in parallel. The circuit for the lower winding of the relay 945 extends from ground, through battery,

winding of relay 945, armature 951 in engagement with its front contact, contact 922 of off-normal switch 920, and armature 953 in engagement with its front contact, to ground. The circuit for the release magnet 952 extends from ground through battery to the winding of release magnet 952, contact 922 of off-normal switch 920, and armature 953 in engagement with its front contact, to ground. Energization of the release magnet 952 mechanically restores the selector to normal but leaves the relay 950 energized through a locking circuit which was established when the relay 950 was energized. This locking circuit extends from ground, through battery, winding of relay 950, front contact and armature 955, armature 956 in engagement with its front contact, to ground.

When the parts are restored to normal, the off-normal switch 920 is also restored to its normal position.

The letter S will now be dialed at the calling station 1. As the letter S is dialed, line relay 905 will be deenergized and energized alternately. At the first deenergization of the line relay 905, its armature 906 moves into engagement with its back contact completing an energizing circuit for the vertical magnet 910 and the slow vertical relay 911 in series as described above in connection with the dialing of the letter T. The vertical magnet is energized and moves the wipers 915, 916 and 917 to the first level of contact and at the same time, the off-normal switch 920 closes its contacts 921 and 922. Closure of contact 921 completes an energizing circuit for the private relay 925 as described above. The vertical magnet 910 is energized and deenergized as the seven impulses comprising the letter S are received and the wipers 915, 916 and 917 are stepped to the seventh level of contacts.

At the end of the impulsion, the line relay 905 remains energized long enough to permit the slow vertical relay 911 to become deenergized. The deenergization of the slow vertical relay 911 moves its armature 927 into engagement with its back contact, preparing a circuit for the rotary magnet 930. If the wipers 915, 916 and 917 have moved onto contacts which are idle, a circuit for relays 925 and 901 in series will be established. This circuit extends from ground, through battery, through winding of the private relay 925, contact 921 of off-normal switch 920, back contact and armature 929, winding of relay 901, and armature 908, in engagement with its front contact to ground. Relays 925 and 901 are so designed that when they are connected in series the current flowing through them is not sufficient to energize relay 925, but is sufficient to energize relay 901. Energization of relay 901 moves its armature 909 and 911 into engagement with their front contacts thereby connecting the line from station 1 through to armatures 956 and 957 of relay 950 and over these armatures, in engagement with their front contacts, to the repeater relay, the relay 950 being still energized.

Relay 212, shown in Figure 4, is energized before slow relay 907 of Figure 20 becomes deenergized so that the locking circuit of the relay 950 instead of extending over armature 908 to ground, extends over the front contact and armature 948 of relay 901, wiper 917, upper contact 197, armature 233 in engagement with its front contact, to ground.

As soon as wipers 915 and 916 are connected to the contacts 197 shown in Figure 4, the line relay 211 will be energized and will close an 75

energizing circuit for the slow relay 212. Energization of relay 212 will extend ground over front contact and armature 233 to the upper contact 197 in engagement with the wiper 917. 5 This ground on wiper 917 appears upon wiper 917 before slow relay 907 has a chance to deenergize. Therefore when slow relay 907 does deenergize, movement of its armature 908 away from its front contact breaks the original locking circuit of relay 10 950, but does not deenergize this relay because this relay now has a new locking circuit which extends from ground, through battery, winding of relay 950, front contact and armature 955, front contact and armature 946, wiper 917, upper contact 15 197 to ground.

The operation of the convertible selector of Figure 20 for telephonic service is the same as the operation of the selector 8 of Figure 3. The 20 relays and magnets 801, 905, 907, 911, 925, 919, 930 and 952 in Figure 20, correspond to relays and magnets 161, 135, 137, 143, 154, 144, 147 and 546, respectively, and in Figure 20. The relays 945, 950, 23 and 411 do not operate for telephonic 25 service.

25 It will be noted from the circuits thus far described, that the polarity impressed upon the conductors extending from each subscriber's station is different for telephony and for telegraphy. Thus, for example, as shown in Figure 1, battery 30 is connected through relay 48 and switch 53 to the conductor 5 for telegraph signalling and is connected through the switch 39 to conductor 6 for telephone signalling. In Figure 6, battery is connected through the relay 48 to the conductor 5 and battery is connected to the conductor 6 for telephony, etc.

This is done in order to prevent the telegraph operator from breaking in on a telephone conversation in the event that his lamp 97 becomes defective and fails to indicate that the telephone apparatus is in operation. Furthermore, while 40 ringing a combination station, such as shown in Figure 7 or Figure 8 for telephone service, the guard lamp 97 is dark and the switch 94 engages its lower contact or armature 381 is closed to its back contact. The telephone user may not hear the telegraph bell ringing and may operate the starting lever to initiate the use of the telegraph set. In that event, the magnet 91 will hold the 45 switch 74 operated until the telephone attendant, having heard the bell, lifts the receiver which deenergizes the magnet 91 and thus releases the switch 74. Due to the polarity of current flowing over the conductors 3 and 4 for telephone connection, as described above, the relay 85 is at 50 this time energized in such a way that it holds its armature to the left maintaining its contact open.

Modified repeater

55 In the repeater system of repeaters 14 and 42, the feed relays 23 and 48 are held in operative condition or energized by reason of the short circuiting of their line circuits while a spacing 60 signal is being transmitted. It may be preferable to hold these relays energized while current is removed from the line for a spacing signal as shown in Figure 22. In this figure, the line feed relay 1000 is shown having three windings. The 65 line circuit extends through the left winding 1001 and the middle winding 1002, the right hand winding 1003 having in series with it a relay 1004, the armature 1005 of which is connected in series with the winding 1002. The relay 1006 has 70 an armature 1007 which controls the circuit of 75

the relay 1004 and the winding 1003. When the relay 1000 is energized its armature 1008 moves into engagement with its front contact completing the alternating current energizing circuit for the relay 1006. Energization of relay 1006 moves 5 its armature 1009 into engagement with its front contact energizing relay 1004 and winding 1003 of relay 1000. Energization of relay 1004 moves 10 its armature 1005 out of engagement with its back contact thereby breaking the line circuit. Energization of the winding 1003 of relay 1000 maintains relay 1000 energized even though the line circuit has been broken and armature 1008 will be maintained in engagement with its front contact. 15

Details

Figure 25 shows the telephone ringer 678 and Figure 26 shows the ringing relay 379. Each 20 of these devices comprises magnets and armatures cooperating therewith and in each case the armature has a tapper.

Ringer 678 comprises electromagnet 1030 having an armature 1031 carrying a tapper 1032. Tapper 1032 has a ball 1033 on its end for ringing 25 the gong 1034.

The ringing relay 379 comprises an electromagnet 1040 having an armature 1041 which carries a tapper rod 1042. On the end of the tapper 1042 is a contact member 1043 which cooperates with the contacts 1044 and 1045. The ringer 678 has a comparatively heavy armature and tapper whereas the relay 379 has a comparatively light armature and tapper. Ringer 678 is designed to respond to an alternating current 30 of 16 cycles per second which is the frequency ordinarily used for ringing on telephone lines. Ringing relay 379 is designed to respond to alternating currents of 100 cycles per second which is the frequency used in some cases for ringing 35 the telephone bell on a partly line. 40

Figure 27 shows one form of polar relay which may be used in lieu of the neutral relays 23 and 48. As shown, it comprises a core 1050 having three windings, 1051, 1052 and 1053. Winding 1051 has one of its terminals connected to the line and the other terminal to battery. Winding 1053 has one of its terminals connected to the line and the other terminal connected to ground. The winding 1052 has one of its terminals connected through an adjustable resistance 45 1054 to the terminal of winding 1051 which leads to battery, and the other terminal of winding 1052 is connected to the terminal of winding 1053 which leads to ground. 50

Modified repeater circuits

Figure 28 shows the repeater system with ground return and all relays for direct current. The system shown is a manual telegraph system. The customary ground return is used, the open circuit section produces a local connecting link and all repeating relays are shown at a single repeating station with two connected line sections. The equipment at the terminal stations may be manual or automatic. Normally the 60 keys 1100 and 1200 are closed, the printing magnets 1101 and 1201, and the relays 1102 and 1202 are all energized. When the key 1100, at the transmitting station is operated to open the circuit, relay 1102 is deenergized and its armature 65 1103 moves into engagement with its back contact, closing an obvious energizing circuit for the relay 1204. Energization of relay 1204 moves its armature 1205 into engagement with its front contact, shunting the printer magnet 1201. 70 75

Printer magnet 1201 deenergizes and registers a "no current" impulse.

When the key 1100 at the transmitting station is depressed to close its contacts, relay 1102 is energized, moving its armature 1103 into engagement with its front contact thereby deenergizing the relay 1204 which moves its armature 1205 out of engagement with its front contact, breaking the shunt circuit. Printer magnet 1201 is then energized in series with the relay 1202 and printer magnet 1201 registers a "current" impulse.

Transmission of signals in the opposite direction takes place in a similar manner. Thus when the key 1200 is operated to open the circuit, relay 1202 is deenergized and its armature 1203 moves into engagement with its back contact, closing an obvious energizing circuit for the relay 1104. Energization of relay 1104 moves its armature 1105 into engagement with its front contact, shunting the printer magnet 1101. Printer magnet 1101 deenergizes and registers a "no current" impulse.

When the key 1200 is depressed to close its contacts, relay 1202 is energized, moving its armature 1203 into engagement with its front contact thereby deenergizing the relay 1104 which moves its armature 1105 out of engagement with its front contact, breaking the shunt circuit. Printer magnet 1101 is then energized in series with the relay 1102 and printer magnet 1101 registers a "current" impulse.

Figure 29 shows the repeater system with the details of Figure 22 substituted in the system of Figure 28. In this system the substitution of the details of Figure 22 permits the use of line batteries at all stations. At the transmitting station, key 1300 is normally depressed to hold its contacts closed and printer magnet 1301 as well as relay 1302 are normally energized. Similarly at the receiving station, the key 1400 is normally in a position to close its contacts and therefore printer magnet 1401 and relay 1402 are normally energized. When the key 1300 at the transmitting station is operated to open its contacts, relay 1302 will be deenergized, permitting its armature 1303 to move to its back contact thereby closing a circuit for the relay 1404 at the repeating station. This circuit extends from ground, through battery, back contact and armature 1303, armature 1403 in engagement with its front contact, relay 1404, to ground. Relay 1404 energizes and moves its armature 1405 into engagement with its front contact thereby closing a holding circuit for the relay 1402. This holding circuit extends from ground, through battery, lower winding of relay 1402, winding of the relay 1406, front contact and armature 1405, to ground. Relay 1406 energizes and moves its armature 1407 away from its back contact thereby breaking the circuit of the printer magnet 1401. The printer magnet 1401 then registers a "no current" impulse. Although the circuit through the upper winding of relay 1402 is broken at the armature 1407, the relay 1402 remains energized because of the holding circuit extending through the lower winding of this relay.

When the key 1300 at the transmitting station is operated to close its contacts, the relay 1302 will be energized and will move its armature 1303 into engagement with its front contact thereby breaking the circuit for the relay 1404. Deenergization of relay 1404 moves armature 1405 away from its front contact breaking the circuit of relay 1406. Deenergization of relay 1406 moves

armature 1407 into engagement with its back contact again completing the circuit through the upper winding of the relay 1402, and the winding of the printer magnet 1401 in series. The printer magnet 1401 is energized and registers a "current" impulse. 5

In a similar manner "current" impulses and "no current" impulses transmitted from the receiving station by operation of the key 1400 are registered at the transmitting station by the printer magnet 1301. Thus, when the key 1400 is operated to open its contacts, relay 1402 will be deenergized, permitting its armature 1403 to move to its back contact thereby closing a circuit for the relay 1304 at the repeating station. 15 This circuit extends from ground, through battery, back contact and armature 1403, armature 1303 in engagement with its front contact, relay 1304, to ground. Relay 1304 energizes and moves its armature 1305 into engagement with its front contact thereby closing a holding circuit for the relay 1302. This holding circuit extends from ground, through battery, lower winding of relay 1302, winding of the relay 1306, front contact and armature 1305, to ground. Relay 1306 energizes 25 and moves its armature 1307 away from its back contact thereby breaking the circuit of the printer magnet 1301. The printer magnet 1301 then registers a "no current" impulse. Although the circuit through the upper winding of relay 1302 is broken at the armature 1307, the relay 1302 remains energized because of the holding circuit extending through the lower winding of this relay.

When the key 1400 is operated to close its contacts, the relay 1402 will be energized and will move its armature 1403 into engagement with its front contact thereby breaking the circuit for the relay 1304. Deenergization of relay 1304 moves armature 1305 away from its front contact 40 breaking the circuit of relay 1306. Deenergization of relay 1306 moves armature 1307 into engagement with its back contact again completing the circuit through the upper winding of the relay 1302 and the winding of the printer magnet 1301 in series. The printer magnet 1301 is energized and registers a "current" impulse. 45

It will be noted in connection with the apparatus of Figure 29 that when a "current" impulse is transmitted, a "current" impulse is registered at the receiving station, and when a "no current" impulse is transmitted, a "no current" impulse is registered at the receiving station. 50

It will be clear from the above descriptions that the telephone service may continue of major importance and the telegraph service remains of minor importance, and accordingly the prior telephone value of the exchange may not be diminished. 55

As will now be understood, the owner of the exchange may offer three classes of service contracts; namely, a telephone line without telegraphic features, a telegraph line without telephone features or combined telephone and telegraph line. The new equipment is of such a 60 nature and its addition such that the telephonic value of the exchange is not diminished and the telegraph and telephonic service makes use in common of much of the prior switches, which were originally utilized for telephonic service only. 65

As will be obvious, the introduction of telegraphic service will result in a greater total traffic, and because of this greater total traffic, it will be necessary to add to the prior number of selectors but the total selectors of any class used 70 75

5 jointly by the two services will be fewer in number than the total for that class of selector would be if the telephonic service were served by selectors not used by telegraphic circuits, and if the telegraphic service were served by selectors not used by telephonic circuits, so that this invention effects considerable economy of switching equipment.

10 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

15 20 What we claim as new and desire to secure by United States Letters Patent, is:—

1. In combination, two stations, a central office, lines connecting said stations to said central office, automatic switches in said central office and controllable by either of said two stations and over which said stations may be connected for telephonic communication, and alternative automatic switches in said central office and controllable by either of said two stations and over which said stations may be connected, said alternative automatic switches containing telegraph apparatus.

25 30 35 40 2. In combination, two stations, a central office through which said stations may be connected, first switching mechanism including telephone apparatus in said central office, second switching mechanism including telegraph apparatus in said central office, means controllable by either of said two stations for connecting together said stations through said central office, said means including alternatively either said first switching mechanism or said second switching mechanism.

35 40 45 50 3. In combination, two stations, a central office, first switching mechanism in said central office, second switching mechanism including telegraph apparatus in said central office, and means whereby the dialing of the directory number determines which of the two switching mechanisms shall be used.

40 45 50 55 4. In combination, a first station, a second station, a first path between the two stations, a second path between the two stations, having communicative characteristics different from the first path, and means controllable from either station for selecting either path to the other station and establishing connections thereto in accordance with the desired communicative service.

50 55 60 65 5. In combination, a first station, a second station, two alternative paths over which said stations may be connected, one of said paths including telegraph apparatus and means whereby the dialing of a certain number at one station will establish connection from that station to the other station over one of the paths and whereby dialing of a different number will establish a connection between the stations over the other path.

60 65 70 75 6. In a selective switching mechanism, a circuit for telegraph communication, a circuit for telephone communication, and means responsive to code combinations of impulse conditions for selecting one of said circuits.

70 75 7. In a selective switching mechanism, a telephone circuit, a telegraph circuit, the telephone circuit being normally operable, and means responsive to code combinations of impulse condi-

tions for rendering the telephone circuit non-operable and rendering the telegraph circuit operable.

8. In a selective switching mechanism, a telephone circuit, a telegraph circuit, a relay for alternately rendering one of said circuits operable and the other circuit non-operable, means responsive to code combinations of impulse conditions for energizing said relay, and means operated by the relay for releasing and restoring said means.

9. In a selective switching mechanism, a telephone circuit, a telegraph circuit, a relay for rendering one of said circuits operable and the other of said circuits non-operable, and means responsive to code combinations of impulse conditions for initially energizing said relay and for subsequently forming a selecting operation.

10. A selective switching mechanism comprising a telephone circuit, a telegraph circuit, a relay for rendering one of said circuits operable and the other circuit non-operable, means responsive to code combinations of impulse conditions for energizing said relay, and means subsequently operative for releasing said relay.

15 11. In a mixed service system, a main line circuit, a switch, a telephone set and a telegraph set alternatively connected to said line by said switch, means for retaining said switch in operated condition, and a timing device for returning said switch to non-operated condition.

12. In a mixed service system, a line circuit, a switch, a telephone set and a telegraph set alternatively connected to said line circuit by said switch, and means operative over said circuit for variably operating said switch.

13. In a mixed service system, a telephone set and a telegraph set, means at the telephone set for indicating when the telegraph set is in operation, and means at the telegraph set for indicating when the telephone set is in operation.

14. In a composite system, a telephone set, a telegraph set, an omnigraph adapted to send the directory number of the station, a telegraph line connected to said telephone set, means responsive to an incoming telegraph call for connecting said telegraph set to said line and for starting said omnigraph into operation.

15. In a composite system, a telephone set, a telegraph set, an omnigraph adapted to send telegraphic signals for the directory number of a station, means responsive to an incoming telegraphic call for preparing said telegraph set for operation and for starting said omnigraph into operation.

16. In a composite switching system for telephonic and printing telegraphic communication comprising a transmitting station having a telephone set and a printer, a first busy signal device adapted to send a signal current for operating said telephone audibly and a second busy signal device adapted to send impulses suitable for operating the printer, means for operating said first device in response to a call for a telephone set upon a busy line and means for operating said second device in response to a call for a telegraph station upon a busy line.

17. In a mixed service system, comprising a combined telephone and telegraph line, a meter associated with said line to register the number of calls made on said telephone line, and a second meter associated with said line to register the number of calls made on said telegraph line.

18. In a mixed service system, comprising a combined telephone and telegraph line, a meter

- associated with said line to register the number of calls made on said telephone line, a second meter associated with said line to register the number of calls made on said telegraph line, and means whereby operation of one of said meters renders the other meter non-operative.
19. In a telegraph system, a first closed circuit line, a second closed circuit line, an open circuit line, a first repeating relay for closing the open circuit line when the first closed circuit line is opened, and a second repeating relay for shunting the second closed circuit line when said open circuit line is closed.
20. In a telegraph system, a first closed circuit section, a second closed circuit section, means to repeat signals from one of said sections into the other of said sections, said means comprising relays and an open circuit section.
21. In a signalling system, a plurality of stations, automatic switching equipment, telegraph and telephone apparatus at each station, and means whereby said automatic equipment operates alternatively to set up telegraphic or telephonic connections between said stations.
22. In a signalling system, a plurality of stations, each having telephone and telegraph apparatus, automatic switching equipment, a line extending from each station to said switching equipment, and means including said switching equipment whereby any of said stations may selectively obtain telegraphic or telephonic communication with the telegraph or telephone apparatus alternatively at any other of said stations.
23. In a signalling system, a plurality of stations each having telephone and telegraph apparatus, the telephone and telegraph apparatus of any one station having assigned to it two individual calling numbers, automatic switching equipment, a line extending from each of said stations to said switching equipment, means for operating said switching equipment to effect a connection to a predetermined station over its line, and means whereby said connection is effected to the telegraph apparatus of said station in response to the dialing of the telegraph number and connection is effected to the telephone apparatus of said station in response to the dialing of the telephone number.
24. In a signalling system, a plurality of stations, a first and second apparatus at each station each having individual numbers assigned thereto, automatic switching equipment, a line extending from each of said stations to said switching equipment, and means including said switching equipment for effecting a connection to the first or second apparatus of any station over the line in accordance with whether the switching equipment is operated in response to the first or second individual number.
25. In a signalling system, a plurality of stations, each having telegraph and telephone apparatus, automatic switching equipment common to said stations, and means whereby the same switching equipment may effect in part a connection between telephone apparatus or telegraph apparatus.
26. In a signalling system, a plurality of stations, each having telegraph and telephone apparatus, a line, said telephone apparatus being normally connected to the line, switching equipment, means whereby a calling subscriber at one station may variably operate said switching equipment for effecting connection to a called subscriber at another station over its line, and means whereby said calling subscriber may effect a disconnection of said telephone apparatus from the line and effect a connection of said telegraph apparatus of said called party to the line.
27. In a signalling system, a plurality of stations, each having first and second apparatus, a line, said second apparatus being normally connected to the line, switching equipment, means whereby a calling subscriber at one station may variably operate said switching equipment for effecting connection to a called subscriber at another station over its line, and means whereby said calling subscriber may effect a disconnection of said second apparatus from the line and effect a connection of the first apparatus of said called party to the line.
28. In a signalling system, a plurality of stations, each having first and second signalling apparatus and an individual line, automatic switching equipment, means whereby a calling subscriber at one station may variably operate said switching equipment, and means controlled by said switching equipment in response to predetermined impulses for effecting a connection from the calling station to the first apparatus of a called station and in response to different predetermined impulses for effecting a connection from the calling station to the second apparatus of the called station.
29. In a signalling system, a plurality of stations, each having telegraph and telephone apparatus, first and second automatic switching apparatus, a signalling line connecting said switching apparatus, means for effecting a connection between the telephone apparatus of two stations and for further operating the switching apparatus for effecting a connection between the telegraph apparatus of two stations, and means operative in the event that a telegraph connection is effected for translating telegraph marking and spacing signals originating at one of said stations into alternating current for transmission over said signalling line.
30. In a signalling system, a plurality of stations, each having telegraph and telephone apparatus, first and second automatic switching apparatus, a signal line connecting said switching apparatus, means for operating the first and second switching apparatus for effecting a connection between the telephone apparatus of two stations and for further operating the switching apparatus for effecting a connection between the telegraph apparatus of two stations, means operative in the event that a telegraph connection is effected for translating telegraph marking and spacing signals originating at one of said stations into alternating currents for transmission over said signalling line, and means at the receiving end of said signalling line for retranslating the alternating currents into direct current marking and spacing signals for operating the telegraph apparatus at the receiving end.
31. In a signalling system, a plurality of lines, each having telegraph apparatus, a plurality of stations, switching equipment, a signalling line connecting said stations, means for variably operating said switching equipment to effect a connection between two of said stations for telegraph communication, means operative following completion of said connection for translating the marking and spacing signals originating at one of said stations into alternating currents for transmission over said signalling line, and means at the receiving end of said line for retranslating said alternating currents into direct current

- marking and spacing signals for operating the receiving station apparatus.
32. In a signalling system, a plurality of stations, each having telephone and telegraph apparatus, a switching equipment including a first connector, and means whereby said first connector operates in response to predetermined impulses from a calling station for effecting a connection to the telephone apparatus of a called station and operates in response to a different number of impulses for effecting a connection to the telegraph apparatus of the called station.
33. In a signalling system, a plurality of stations, each having telephone and telegraph apparatus, switching equipment including a selector repeater, means operating said switching equipment to effect a connection between telephone apparatus of a calling and called station and for operating said switching equipment to effect a connection between the telegraph apparatus of a calling and a called station, and relay means controlled by said selector repeater and operated in the event of a connection between the telegraph apparatus of a calling and a called station for preventing further operation of the switching apparatus.
34. In a signalling system, a plurality of stations, each having first and second apparatus, a switching equipment including a first connector, and means whereby said first connector operates in response to predetermined impulses from a calling station for effecting a connection to the first apparatus of a called station and operates in response to a different number of impulses for effecting a connection to the second apparatus of the called station.
35. In a signalling system, a plurality of stations, having telegraph and telephone apparatus, a source of power for said telegraph apparatus normally in non-operating condition, switching equipment, means at each station for operating the switching equipment and for simultaneously rendering the source of power effective, means for variably operating said switching equipment to effect a connection between the telegraph apparatus at said station and another station, and means at said latter station responsive to said connection for starting the source of power at said latter station into operation.
36. In a signalling system, a plurality of stations, automatic switching equipment, telegraph and telephone apparatus at each station, means whereby said automatic switching equipment sets up telegraphic or telephonic connections between said stations, and means for recording the number of telegraph and telephone connections effected.
37. In a signalling system, a plurality of stations, automatic switching equipment, telegraph and telephone apparatus at each station, means whereby said automatic switching equipment sets up telegraphic or telephonic connections between said stations, means for recording the number of telegraphic and telephonic connections effected, and means whereby the telephone recording means is non-effected by the telegraphic connections and the telegraph recording means is non-effected by the telephonic connections.
38. In a signalling system, a plurality of stations, each having telephone and telegraph apparatus suitable for telephonic or telegraphic intercommunication between stations, automatic switching equipment, an individual line extending from each station to said switching equipment, means including said switching equipment whereby any of said stations may selectively obtain connection with the telegraph or telephone equipment at any other of said stations over the line of the selected station, and indicating means associated with the telegraph and telephone apparatus at each station for indicating at one apparatus when the line of the station has been seized by the other apparatus.
39. In a signalling system, a plurality of stations, automatic switching equipment, telegraph and telephone apparatus at each station, means whereby said automatic switching equipment sets up telegraphic or telephonic intercommunications between said stations, and means for indicating at each station following an intercommunication whether a telegraphic or telephonic connection has been effected.
40. In a telegraph switching system, a closed circuit line, an open circuit line, a repeater system connecting said lines to supply current to said open circuit line in response to opening said closed circuit line and to disable said closed circuit line in response to current in said open circuit line, and automatic switches controlled over said closed circuit line and operating to switch said open circuit line, said open circuit line being without current while being switched and thereby maintaining said closed circuit line in able condition during the time of switching.
41. In a telegraph switching system, an automatic switch, operating magnets and operated brushes in said switch, a subscriber-loop controlling said magnets, circuit wires pertaining to said brushes, and a telegraph repeater connected at all times between said subscriber-loop and said circuit wires.
42. In a telegraph repeating system, a normally closed subscriber-loop, automatic switches, normally closed circuits controlling said automatic switches, telegraphic apparatus, normally open circuits controlling said telegraphic apparatus, and a single repeater connecting said loop to said normally closed circuits and to said normally open circuits.
43. In a telegraph repeating system, a primary normally closed circuit, a secondary normally closed circuit, a secondary normally open circuit, automatic switches controlled by one of said secondary circuits; telegraph apparatus controlled by the other of said secondary circuits, and a repeater connected to said primary circuit and to both of said secondary circuits whereby signals originating in said primary circuit are repeated into both of said secondary circuits.
44. A system as in claim 43 in which also signals originating in said normally open circuit are repeated into said primary circuit.
45. In a printing telegraph exchange system, a first station, a second station, a line normally open to direct current connecting said stations, an alternating current relay connected in said line at said second station and responsive to alternating current applied to said line at said first station for closing said line to direct current, and means controlled by said alternating current relay for removing said alternating current relay from said line.
46. In a printing telegraph exchange system, a first station, a second station, a printer at said second station and a motor for driving said printer, a line normally open to direct current connecting said stations, means for closing said line to direct current, means responsive after said closure for starting said motor, and means operable when said motor has reached operating

speed for causing an indication at the first station that said motor is running.

47. In a printing telegraph exchange system, a second station, a line normally open to direct current connecting said stations, an alternating current relay connected in said line at said second station and responsive to alternating current applied to said line at said first station for closing said line to direct current, means responsive after said closure for removing said alternating current relay from said line and for conditioning said second station for communication with said first station, and means under control of said first station for reconnecting said relay to said line.

48. A printing telegraph exchange system comprising a first station, a second station, a line normally open to continuous direct current connecting said stations, a relay connected in said line at said second station and responsive to current impulses applied to said line at said first station for closing said line to direct current, means operating upon said closure for removing said relay from operative relation with said line and for setting said second station in a condition suitable for communication with said first station, and means controlled over the line which connects said stations for reconnecting said relay to said line.

49. In a printing telegraph system, a central station and a subscriber's station, a teletypewriter including a driving motor at said subscriber's station, a line connecting said stations, said line being normally open to continuous direct current, means for closing said line to continuous direct current, and means operable from said central station for operating said means for closing said line and for starting said motor.

50. In an electrical control system, the combination with a plurality of sets of apparatus for transmitting current impulses, a transmission circuit therebetween normally open to continuous direct current, and separate sources of electrical energy having different current characteristics, of circuit controlling devices at a station selectively through said transmission circuit to differences in the current characteristics of said sources for successively selecting a set of apparatus and establishing, maintaining and discontinuing the connection thereof to said transmission circuit.

51. In an electrical control circuit, the combination of a plurality of sets of apparatus for transmitting separate current impulses, a transmission circuit therebetween, and separate sources of electrical energy having different current characteristics, of means responsive to differences in the current characteristics of said sources for selectively establishing and maintaining communication between different sets of transmitting apparatus.

52. In an electrical control circuit, the combination with a plurality of sets of apparatus for transmitting separate current impulses, a transmission circuit therebetween and separate sources of electrical energy having different current characteristics, of circuit controlling devices selectively responsive to differences in the current characteristics of said sources for establishing and maintaining communication between different sets of transmitting apparatus.

53. In an electrical control circuit, the combination with a plurality of sets of apparatus for transmitting current impulses, a transmission circuit therebetween and separate sources of unidi-

rectional and alternating current, of circuit controlling devices responsive individually to current from said sources for selectively establishing and maintaining connection between different sets of said apparatus through said transmission circuit.

54. In an electrical control circuit, the combination with a plurality of sets of apparatus for transmitting current impulses, a transmission circuit therebetween and separate sources of unidirectional and alternating current, of circuit controlling devices selectively responsive to current from said sources for establishing a connection between different sets of apparatus and maintaining said connection for the transmission of discontinuous current impulses therebetween.

55. In an electrical control circuit, the combination with a plurality of sets of apparatus for transmitting current impulses, a transmission circuit therebetween and separate sources of unidirectional and alternating current, of devices for controlling the connection between separate sets of transmitting apparatus, said controlling devices being responsive to both unidirectional and alternating current, either alone or in combination.

56. In an electrical control circuit, the combination with a central station, separate sources of unidirectional and alternating current at said station, a sub-station providing transmitting apparatus, a single circuit between said stations, of relays individually responsive to unidirectional and alternating current at said sub-station for establishing and maintaining the connection between said stations.

57. In an electrical control circuit, the combination with a central station, separate sources of unidirectional and alternating current at said station, a sub-station providing transmitting apparatus, a single circuit between said stations, of relays individually responsive to unidirectional and alternating current for establishing an initial connection between said stations, and means for automatically maintaining the connection during the transmission of discontinuous current impulses between said stations.

58. In a telegraph system, a calling and a called subscriber's station, a printer at each of said stations, a central station through which said subscribers' stations can be interconnected, and means at the central station and at the called subscriber's station responsive to the progress of operations in extending a call from the calling to the called subscriber's station for transmitting signals indicative of said progress to the printer at said calling subscriber's station.

59. In a communication system, a first station, a source of alternating current at said station, a second station, a printer and a printer motor at said station, a line normally open to direct current connecting said stations, an alternating current relay at said second station responsive to current from said source when the latter is connected to said line, and a relay in a local circuit at said second station responsive to the operation of said alternating current relay for closing said line to direct current over a circuit including said printer and for starting said printer motor.

60. In a communication system, a first station, a source of alternating current and a source of direct current at said station, a second station, a printer and a printer motor at said station, a line normally open to direct current connecting said stations, means at said second sta-

tion, responsive to current from said alternating current source when the latter is connected to said line for closing said line to direct current over a circuit including said printer and for 5 starting said printer motor, means at said first station for thereafter substituting said direct signalling current for said alternating current, means at said first station for reversing the direction of said line current, and means at said second station 10 responsive to said current reversal for re-opening said line to direct current and for stopping said printer motors.

61. In a communication system, a first station, a source of alternating current and a source of 15 direct current at said station, a second station, a polar relay, a printer and a printer motor at said station, a line open to direct current connecting said stations, means at said second station responsive to current from said alternating 20 current source when the latter is connected to said line for closing said line to direct current over a circuit including said printer and said polar relay, for starting said printer motor and for locking said line and printer motor circuit by means 25 under control of said polar relay.

62. In a communication system, a first station, a second station, a polar relay, a printer and a printer motor at said second station, a line open to direct current connecting said stations, means for closing said line to direct current over a circuit including said printer and said polar relay, for starting said printer motor and for locking said line and the circuit of said printer motor by means under control of said 30 polar relay, and means at said first station for reversing the current in said line to operate said polar relay whereby said line is re-opened to direct current and the circuit of said printer motor is opened.

63. In a communication system, a first station, a source of alternating current and a source of 40 direct current at said station, a second station, a printer and a printer motor at said station, a line open to direct current connecting said stations, means at said second station responsive to current from said alternating current source when the latter is connected to said line for closing said line to direct current over a circuit including said printer and for starting said 45 printer motor, and means comprising line current reversing means at said first station, and a polar relay at said second station for re-opening said line to direct current and for stopping said printer motor.

64. In a communication system, a first station having a source of alternating current, a second station connected thereto by a line normally open to direct current, said second station having a printer, a printer motor, an alternating current 50 relay responsive to current from said source when the latter is connected to the line, and a relay in a local circuit responsive to the operation of the alternating current relay, for closing the line to direct current, for starting the printer 55 motor, and for preparing the closed line circuit to be re-opened and the printer motor to be stopped by means under control of the first station.

65. A telegraph system comprising a first station, a second station, a line normally open to 70 direct current connecting said stations, telegraph apparatus at said second station normally disconnected from said line, a source of alternating current at said first station, and an alternating current relay at said second station re-

sponsive to the connection of said source to said line for connecting the telegraph apparatus at said second station to said line.

66. A printing telegraph system comprising a 5 first station, a second station, a line normally open to direct current connecting said stations, a printer at said second station normally disconnected from said line, a motor for operating said printer, means under control of said first station for connecting said printed to said line 10 and for starting said motor.

67. A printing telegraph exchange system comprising a central station, a source of alternating current at said station, a sub-station, a line normally open to direct current connecting said stations, said sub-station having a printer normally disconnected from said line, a motor for operating said printer, and an alternating current relay, operable by current from said source when the latter is connected to said line, for 20 connecting said printer to said line, and means thereafter operable for closing the operating circuit of said motor.

68. In a printing telegraph exchange system, a 25 plurality of subscribers' stations, printing telegraph transmitting and receiving mechanisms at each of the stations, a central office, means at said office for establishing connections between said subscribers' stations as desired, and automatic means operating on extending a connection to a desired station for sending back to the calling station signals which characterize the desired station, said automatic means being arranged to operate said receiving mechanism at the calling station.

69. In a printing telegraph exchange system, a plurality of subscribers' stations, printing telegraph transmitting and receiving mechanisms at each of the stations, a central office, means at 40 said office for establishing connections between said subscribers' stations as desired, and automatic means which, upon the extension of a connection to a desired station, will produce groups of impulses characterizing the desired station for operating said receiving mechanism at the 45 calling station, the operation of said automatic means being effected when engaging the desired station.

70. In a printing telegraph exchange system, a 50 plurality of subscribers' stations, printing telegraph transmitting and receiving mechanisms at each of the stations, a central office, means at said office for establishing connections between said subscribers' stations as desired, and automatic means which, upon the extension of a connection to a desired station, will produce groups of impulses characterizing the desired station for operating said receiving mechanism at the calling station, the operation of said automatic 55 means being effected by means of a relay becoming operative when engaging the desired station.

71. In a printing telegraph system, a plurality of subscribers' stations, printing telegraph transmitting and receiving mechanism at each of the stations, a central office for establishing connections between said subscribers' stations as desired, and automatic transmitting means operating on extending a connection to a desired station for sending out to a calling subscriber's 65 station a predetermined series of impulse combinations characterizing a called station, said automatic transmitting means consisting of signal producing means representing a series of impulse combinations in a fixed form, and of distributing means for sending out said impulse 70 75

combinations in identical manner corresponding to the transmission of the message impulse combinations.

72. In a call recording and charging system, calling and called subscribers' lines, means for establishing a connection between a calling line and a called line, means automatically operative responsive to the establishment of said connection in case the called line is idle for transmitting back over the established connection an identification signal assigned to the called subscriber's line, and a recorder associated with said calling line operated responsive to said transmission for recording said called line identification signal.

73. In a call recording and charging system, calling and called subscribers' lines, means for establishing a connection between a calling line and a called line, means responsive to the establishment of said connection for transmitting an identification signal assigned to the called subscriber's line, and a recorder associated with said calling line operated responsive to said transmission for recording said called line identification signal.

74. In a call recording system, calling and called subscribers' stations, a line for connecting said stations, means for establishing an operative connection over said line between said stations, means responsive to the establishment of said connection for transmitting an identification signal assigned to a called station, and a recorder associated with the line at the calling station operated responsive to said transmission for recording the called station identification signal.

75. A printing telegraph exchange system comprising a plurality of stations, a source of alternating current at one of said stations, a line normally open to direct current connecting said stations, one of said stations having a printer normally disconnected from said line, a motor for operating said printer, an alternating current relay operable by current from said source when the latter is connected to said line for connecting said printer thereto, and means thereafter operable for closing the operating circuit of said motor.

76. A telephone system comprising a plurality of subscribers' stations each associated with a pair of talking circuit conductors and comprising telephone communication equipment connected thereto, each of said stations also comprising apparatus whereby, when connected to a similar station, teleprinter communication unlimited in its content may be carried on over the talking circuit conductors, means at each subscriber's station connected to the talking circuit conductors at all times when the respective subscriber's station is idle for giving a call signal at a called station in response to calling currents incoming over the talking circuit conductors whereby a called subscriber may be summoned to his station to respond to a telephone call, and means whereby without previous disturbance of the normal connection of the telephone communication equipment to its talking circuit conductors, the teleprinter equipment at an unattended called station may be connected by remote control to the talking circuit conductors and may be conditioned to receive and record a telegraph message.

77. A telephone system comprising a plurality of subscribers' stations each provided with an incoming talking circuit, a subscriber's set normally associated therewith and teleprinter equipment by

which teleprinter communication unlimited in its content may be carried on over the talking circuit, a movable contact device for alternately connecting the telephone subscribers' set and the teleprinter equipment to the incoming talking circuit, means at each subscriber's station connected to the incoming talking circuit at all times when the respective subscriber's station is idle for giving a call signal in response to calling currents received over the incoming talking circuit whereby the subscriber at the respective station may be summoned to respond to a telephone call, and remotely controlled means whereby the teleprinter equipment at an unattended called station may be connected to the talking circuit and conditioned to receive and record a telegraph message.

78. A combined telephone and telegraph system comprising a plurality of subscribers' stations, each provided with a printing telegraph transmitter and a printing telegraph receiver adapted for transmission of telegraphic messages of unlimited content, each of said stations also comprising telephone transmitting and receiving apparatus, a central office, talking circuit conductors connected to each of said subscribers' stations and terminating at said central office, means at each of said stations to enable the subscribers at two connected stations to carry on either telephone communication or telegraph communication at will, means at each subscriber's station connected to the talking circuit conductors at all times when the respective subscriber's station is idle for giving a call signal at the subscriber's station in response to calling currents incoming over the talking circuit conductors whereby a called subscriber may be summoned to his station to respond to a telephone call, and means whereby the subscriber at a calling station without any previous disturbance of the normal connection of the telephone transmitting and receiving apparatus of a remote unattended called station to its local talking circuit conductors may directly control the apparatus of the unattended called station to connect up the printing telegraph receiver thereto and to cause it to record telegraphic messages of unlimited content.

79. A telephone system comprising a plurality of subscribers' stations each provided with a local telephone circuit, telephone subscribers' apparatus normally connected thereto, means at each subscriber's station connected to the local telephone circuit at all times when the respective subscriber's station is idle for summoning a called subscriber to the station in response to incoming calling currents, printing telegraph equipment at each of said stations by means of which telegraphic communication unlimited in its content may be carried on between two connected telegraph equipments over the local telephone circuits associated with said stations, said telegraph connection including means for transmitting telegraph signals as impulses of a single voice frequency current, and means whereby without previous disturbance of the normal connections of the telephone subscribers' apparatus at an unattended called station the telegraph equipment thereto may be connected to the local circuit and conditioned to receive and record a telegraph message.

CERTIFICATE OF CORRECTION.

Patent No. 2,153,574.

April 11, 1939.

EDWARD E. KLEINSCHMIDT, ET AL.

It is hereby certified that error appears in the printed specification of the above numbered patent requiring correction as follows: Page 5, first column, line 11, strike out "the"; line 26, for "state dabove" read stated above; page 8, first column, line 60, for the reference numeral "193" read 293; page 12, first column, line 35-36, for "releases" read release; and second column, line 8, for "contact 510" read contact 520; page 16, second column, line 4, for the reference numeral "40" read 140; page 19, second column, line 40, for "partly" read party; page 24, first column, line 10, claim 47, for "alterating" read alternating; line 46, claim 50, after "selectively" insert responsive; page 25, second column, line 10, claim 66, for the word "printed" read printer; and that the said Letters Patent should be read with this correction therein that the same may conform to the record of the case in the Patent Office.

Signed and sealed this 13th day of February, A. D. 1940.

(Seal)

Henry Van Arsdale,
Acting Commissioner of Patents.
